UNITED STATES PATENT OFFICE

CHARLES W. GREEN, OF ILION, NEW YORK, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Application filed March 6, 1925. Serial No. 13,470.

This invention relates generally to cash registers of the key operated type and particularly to that class adapted to totalize a series of items and employing printing devices for obtaining the printed totals and other information.

More specifically, it is a primary object of the present invention to provide an accounting machine which will be simple and inexpensive to manufacture and which will be capable of producing a printed record of all of the data necessary for the protection of the proprietor of a store in which the machine is to be employed. Thus, in addition to providing a printed record of the total amount of sales during a given period the machine of the present invention contemplates the production of an accurate printed record of the number of times that the totalizing device has been reset. With this record the proprietor, who is normally the only person authorized to perform a resetting operation is at once notified of any attempt on the part of a dishonest clerk to erase an amount from the totalizer since the last record of the total was printed. This phase of the invention is specially suited as well to a system of chain stores in which an auditor is normally the only authorized person to reset the totalizer, while the manager of a particular store may be permitted to print a daily record of totals. Other desirable printed information is also available by the present invention as, for example, a record of the total number of operations of the machine as well as of the "no sale" operations which together, by mere mental subtraction, will disclose the number of actual sales, while means for identifying the record by date or similar suitable designation is also contemplated. Many detailed improvements are incorporated in the printing section of the machine and among these may be mentioned the provision of special designation printing blocks adjacent each group of printing elements, and the provision of simple and readily replaceable inking members which will require no connection to the operating portions of the machine for the purpose of feeding or shifting.

In order that the machine adapted to carry out the foregoing objects may be properly safeguarded so that only authorized persons may have access to the various special features and so that misoperations either intentional or accidental may be minimized or entirely eliminated, it is an object of the present invention to provide a system of locks and interlocks of simple but effective construction. To this end the invention contemplates the use of a single lock to control the opening of a lid which normally conceals various controlling elements, which determine the performance of the various functions of the machine. For example, a general control member, such as a lever, may be located under the lid for determining whether the machine shall be operated regardless of the position of a cash drawer, or shall require the closing of the drawer between successive operations, or whether the machine shall be locked against all operations, or shall be condition for total printing and resetting. It is also contemplated that a resetting lever shall be provided under the locked lid so that under proper conditions the proprietor or other person having control over the lid lock shall be able to reset the various registering elements. The placing of the total printing mechanism as well as the bell muffler control under the same locked cover is in accordance with the object to simplify the protection of these features.

In connection with the various operable elements of the machine, such as the operating keys, the general control lever, the resetting mechanism, and the printing mechanism, it is an object to provide a simple and effective locking and interlocking system to properly regulate their operation. For example, the system may be so designed that in certain positions of the control lever none of the remaining elements may be operated, whereas in other positions of this lever merely the operating keys may be operated either dependent upon or independent of the position of the cash drawer, while in still another position of the lever only the operating keys are locked while any one, but only one, of the remaining operable elements may be operated.

To this end it is a part of the invention to employ a series of pivoted and sliding elements to serve both as a lock for certain members under control of the general control lever 5 and as an interlock to prevent the operation of more than one of a plurality of members, which may be free to be operated.

In a modified form of the invention, which is particularly suited for the auditor's type of machine before mentioned, it is contemplated that a second lock should readily be adapted for addition to the machine so that either of a pair of locks may control the release of the lid, previously mentioned, while one lock only 10 is adapted to release the resetting mechanism for operation after the lid is opened and the control lever is shifted to the proper position. In the simplification of this mechanism it is 15 a part of the present invention to employ a single member under the control of both locks and adapted to be differently controlled by each so that one lock serves to unlock the lid and the control lever while the other lock serves to release the resetting mechanism in 20 addition to the lid and control lever.

The present invention embraces also a number of novel and effective features in connection with its resetting mechanism, and among these are the provision of a single 25 lever for causing the simultaneous resetting of a plurality of registering devices mounted on separate shafts; connections from a single lever to first cause a lateral shifting and then a rotation of a totalizer resetting shaft to 30 restore the elements to zero; means for preventing the rotation of the shaft until it has been properly shifted, this means being so designed as to limit the rotation of the shaft; and connections from the resetting mechanism 35 to a special counter whereby the latter will count only effective resetting operations, this being accomplished by merely conditioning the counter for operation upon a subsequent operation of the machine when the 40 resetting mechanism has been operated.

Many other objects and advantages of the present invention will appear from the detailed description of a preferred embodiment which will hereinafter be given and among 45 these may be suggested the mechanism for engaging the totalizer with the actuators and its relation to other features of the machine; improved special counter operating mechanism; improved latching and releasing means for a lid as well as means for holding the lid in any set position; and various improved 50 details of construction of all features of the machine, particularly the total printing means, the resetting mechanism, and the interlocking devices.

With these and incidental objects in view the invention consists in certain novel features of construction and combination of parts, the essential elements of which are set 55 forth in the appended claims, and a preferred

form of embodiment of which will now be described with reference to the drawings which accompany and form part of the specification.

Of said drawings:

Fig. 1 is a view in perspective of the machine to which the present invention is applied showing the arrangement of the operating keys. It also shows the control lever, the resetting lever, the printing button for effecting printing impressions and also the hinged cover for preventing unauthorized persons from having access to these parts. 70

Fig. 2 is a top plan view of the machine, the cabinet having been removed. This view shows substantially all the devices embodied in the machine and the relation which they bear to each other. 75

Fig. 3 is a section of the machine taken substantially through its mid-portion. This view shows particularly the differential and totalizing devices and their relation to each other, as well as a section through the printing mechanism provided for effecting printing from the printing type. 80

Fig. 4 is a section through the machine taken on the line 4-4 of Fig. 2 and shows the "No sale" key, and a portion of the printing mechanism together with the interlocking devices related with the resetting and control lever. This view shows how the control lever controls the locking devices when desired to require the closing of the cash drawer before a subsequent operation can be effected. 85

Fig. 5 is a view taken in a plane substantially parallel to the shafts which support the printing type, showing the totalizer, date setting wheels and special counters. This view also shows the resetting means common to the totalizer and special counters. 90

Fig. 6 is a sectional view showing the totalizer engaging devices as well as a section through the "reset" counter illustrating the details of construction of the latter. 100

Fig. 7 is a section of the machine showing the control lever in the "total" position and its effect upon the key locking devices and drawer release mechanism. 110

Fig. 8 is a sectional view similar to Fig. 7, but with the reset lever partially operated 115 showing how the interlocking devices come into play.

Fig. 9 is a section taken just to the right of one of a pair of intermediate frames showing the lid releasing devices and the lock for the printing mechanism. This view also illustrates the bell sounding mechanism and the lever for disabling the same. 120

Fig. 18Z is an example of printing performed by the machine after the resetting 20 operation has been performed.

Fig. 19 is a detail of the totalizer shaft shifting devices, effective during resetting operations.

25 Fig. 20 is a sectional view showing the relation between the totalizer "pick-up" pawls and the shifted totalizer resetting shaft.

Fig. 21 is a sectional view through the totalizer element showing the normal relation 30 between the "pick-up" pawls and associated resetting shaft.

Fig. 22 is a sectional view taken on the line 22-22 of Fig. 5.

Fig. 23 is a top plan view of a portion of 35 the cabinet cover and the attached index strip associated with the reset and control levers.

Fig. 24 is a perspective view of an assembly of the totalizer resetting shaft.

40 Fig. 25 is a view of the resetting gear common to the resetting shafts showing particularly how one of the associated gears is aligned during the resetting operation.

Fig. 26 is a detail view of the shaft for 45 unlocking the levers in combination with multiple locks whereby they can be unlocked singly or together.

Fig. 27 is a detail of one of the special 50 printing blocks provided for the purpose of identifying the totals printed by the special counters.

For convenience of description the principal elements of the machine will first be 55 enumerated and their general purpose, arrangement and co-operation will be briefly explained in order to indicate the general operation of the machine as a whole, after which the preferred construction of these parts will be described more in detail together with the function, construction and operation of certain secondary or accessory mechanisms associated therewith.

Briefly, stated in general terms the invention relates to a key operated cash register having a plurality of banks of amount keys 60 and a special key designated as a "No sale"

key. All of the amount keys have connections to indicator tablets and furthermore operate a differential mechanism so as to insert the item in a totalizer. As is usual in this class of machines when the keys are operated they 70 are connected to a key coupler which has connections to elevate an indicator flash and drive a power shaft from which the various parts of the mechanism are operated.

During each operation of the machine a 75 unit is entered in a counter designated as the "Customer" counter and each time that the "No sale" key is operated its associated counter will also be operated.

In order to operate the machine in different 80 ways, such as, by requiring the cash drawer to be returned before the keys may subsequently be operated, or by permitting the machine to be successively operated irrespective of the position of the cash drawer, 85 a single lever is provided for controlling suitable mechanisms. Movement of this lever to another position furthermore will totally lock the keys against manipulation.

At the termination of a day's business the 90 same "control lever" is brought to the position designated as a "Total" position in which the machine is conditioned for total printing and resetting and simultaneously the cash drawer is released.

95 In order to print the totals and the information standing upon the totalizer, the special counters, and a series of date printing wheels, a suitable printing mechanism is provided, which is operated by the depression of 100 a knob extending from the front of the printer casing.

After printing, the paper is simply drawn out and detached from the rest of the roll. Upon completion of the printing operation, 105 the resetting lever is manipulated and all the elements of the totalizer and counters will be restored to zero with the exception of those belonging to the "reset" counter. The control lever is then brought back to one of the adding positions and upon a subsequent operation of the machine the "reset" counter operating means which has been shifted during the resetting operation will be operated so as to 110 denote a unit to the counter to cause it to denote a 115 reset number corresponding to the next series of sales registered.

In order to lock the various manipulative devices against unauthorized operation a 120 hinged cover is provided which, when securely locked prevents access to said levers.

The machine as shown in the drawings is provided with a single exterior lock for obtaining access to the levers located under the cover, but a modification is also shown whereby a supplemental lock may be provided so that either may unlock the cover, while the control and rest levers which are normally locked against operation by a common locking rod are unlocked either singly or together 125 130

depending upon which of the pair of the exterior locks has been operated.

In order to insure that the manipulative devices are not operated improperly suitable interlocking devices are provided so they cannot be operated simultaneously. This insures the proper recording of the amounts and that the printing and resetting operations have been performed correctly.

10 The general organization and operation of the machine as a whole having been thus outlined the preferred construction of the various parts above referred to will now be described more in detail.

15 *Framework*

The various parts of the mechanism are supported by a suitable framework comprising a base 20 and parallel side frames 21 and 22 (Fig. 2). Extending between the rearward end of the frames 21 and 22 is a supporting frame 23 utilized to support the indicating and other mechanism. The side frames 21 and 22 are rigidly connected together at their forward ends by a bar 24. Extending between the supporting bar 23 and the bar 24 and parallel to the frames 21 and 22 are frames 25 and 26, the front ends of which are bifurcated at 27 to engage a shaft 28 passing through ears integral with the bar 24. The upper rear ends of the side frames 25 and 26 rest against the frame 23 while the lower rear ends of the frames 25 and 26 are apertured to receive a shaft 29 which passes through ears integral with the framework 23. The intermediate frames 25 and 26 are furthermore suitably joined together by means of shafts and other connections which will be referred to hereinafter.

40 As best shown in Fig. 1 the mechanism is enclosed by a cabinet 30 which may be made of any desired material. The cabinet 30 is slotted at 31 to receive the forward end of the key levers and is furthermore apertured at its upper end so as to permit the viewing of the raised indicators. The printing and other associated mechanisms are concealed by means of a cover 31' which is rigidly attached to the cabinet 30, but is apertured 45 so as to permit the access to some of the parts. In order to completely conceal and to prevent unauthorized persons from having access to the printing devices and controlling levers these are adapted to be covered by 50 means of a cover 32 hinged to the cabinet 30 and so arranged that when this cover is securely locked access cannot be had to any of the controlling devices.

60 *Keys and key coupler*

The illustrative machine is provided with a number of keys divided into groups (Figs. 1 and 2) one group for registering amounts from 1¢ to 10¢, another group for amounts ranging from 10¢ to 90¢ and a third group

for registering values of \$1.00 and \$2.00 amounts. A special key is also provided and is designated as the "No sale" key 33, the function of which is to release the cash drawer to make change, etc. The amount 70 keys 34 and "No sale" key 33 are pivoted upon a shaft 35 (Fig. 3) journaled between the side frames 21 and 22 and resting upon the rear ends of the keys is a key coupler 36 provided with a nose 37 co-operating with 75 notches 38 formed in the rear ends of each of the operating keys. When the forward ends of the operating keys are depressed the key coupler is rocked clockwise and the nose 37 enters the notches 38 of the depressed keys. 80 The purpose of such key coupler mechanism is well known in the art and will not be discussed herein in detail.

Connected to the key coupler at 39 is a vertical reciprocating rack plate provided 85 with rack teeth 41 which alternately mesh with a gear 42 (Fig. 2) fast to a shaft 43. The arrangement of this mechanism is such that a reciprocation of the key coupler 30 by the keys will effect a complete rotation 90 of the gear and the shaft 43 to which the gear 42 is secured. This mechanism is also well known in the art and shown in many patents and one form which this mechanism might take is illustrated in detail in the patent to Thomas Carney, #482,461 dated September 6, 1892.

After a registration has commenced it is essential that some device be provided to insure a complete performance of the started 100 registration before a second operation can subsequently be effected. To this end any suitable mechanism can be provided, but in the present instance it comprises a spring-pressed pawl 44 (Fig. 2) bearing against a 105 ratchet wheel 45 secured to the main operating shaft 43.

Differential mechanism

The differential mechanisms or devices 110 controlled by the various groups of keys for entering the desired amounts in the totalizers are all similar in construction and principle and a description of one will suffice for all. Each amount key 34 associated with the dimes group of keys (Fig. 3) is provided with an upwardly extending arm 46 carrying a suitable anti-friction roller 47 co-operating with a differential slot 52 formed in a cam plate 48. Loosely mounted upon a transverse 115 shaft 49 which is journaled between the machine side frames is a frame 50 provided with spaced slots in which are secured by means of pins 51, a series of the cam plates 48. The cam plates 48 are formed with L shaped slots 52 and 53, the slots 53 being concentric with respect to the shaft 49. The slots 52 are, however, graduated so that when the roller 47 carried by the arm 46 of a depressed key operates in the cam slot 52 of 120

its associated cam plate 48 it will move the frame 50 differentially and to an amount commensurate with the value of the key depressed. When, however, the frame 50 is rocked by the depression of a key 34 of a certain group, the rollers 47 related to the undepressed keys of that group will play in the arcuate slots 53 of their respective cam plates 48, thereby permitting the frame 50 to be rocked differentially without interference from the rollers 47 of the unoperated keys.

It is to be understood that there is a differential frame for each group of amount keys and that the differential frames associated with the three groups of amount keys have attached thereto a segmental rack 54 (Fig. 3). From the above it will be evident that since there may be nine keys in a particular group and a corresponding number of cam plates 48 the segmental rack 54 may be rocked to any one of nine different positions by the depression of a key 34 associated with such group of keys. Depression of keys in two or more groups of keys will similarly adjust the plurality of associated segmental racks differentially so that this movement can be transferred to the totalizer pinions in the manner which will now be described.

30 Totalizer engaging mechanism

The totalizer embodied in the machine shown in the drawings comprises a frame 55 (Figs. 2, 3 and 5) which is journaled in the intermediate frames 25 and 26 by means of journal pins 56 passing through the intermediate frames 25 and 26 and into sockets formed in the totalizer frames. These pins are the pivotal points of the totalizer frame and the frame is adapted to be rocked about these points as a center to bring the totalizer pinions in mesh with the actuating racks 54 at the proper time. The totalizer may be made up of any desired number of numeral elements but as illustrated comprises a series of seven wheels 57 loosely mounted upon a shaft 58 journaled in the totalizer frame 55, and the peripheries of these wheels are formed with raised characters so as to effect printing upon a suitable impression material. Each printing wheel 57 has attached thereto a pinion 58', three of which are adapted to mesh with the teeth of the segmental racks 54 hereinbefore referred to.

55 In order to mesh the pinions 58' with the segmental racks 54 the following mechanism is provided, reference being had particularly to Figs. 3, 5 and 6. Slidably mounted on the left hand journal pin 56 is a bar 59 which is connected at its rear end to the mid-point of an arm 60 pivoted on a stud extending to the left side of the frame 25. The lower end of the arm 60 carries a stud adapted to engage a slot formed in a box cam 61 fast to

the rotation shaft 43 while the forward end of the bar 59 is bifurcated to engage the shaft 58 which it will be remembered carries the totalizer wheels and pinions.

During the downward stroke of the keys 70 the shaft 43 will be rotated in the direction of the arrow shown in Fig. 6 and due to the configuration of the slot in the box cam 61 the bar 59 will be drawn rearwardly early in the depression of the keys so as to rock the 75 totalizer frame 55 about its pivotal point 56 to bring the totalizer pinions in mesh with the racks 54 which are then differentially operated under control of the keys. During the return stroke of the keys the box cam will 80 again act upon the bar 59 forcing it forward thereby withdrawing the totalizer pinions from engagement with the actuating racks 54 and leaving the pinions 58' in their differentially adjusted positions.

85 In machines of the class under consideration, it is also essential that transfer devices be provided for carrying a unit from lower to higher order wheels of the totalizer and any suitable means may be provided for this purpose. Inasmuch as this mechanism forms no part of the present invention it will not be described herein.

Indicators and flash 95

It is desirable that when a key is operated some means be provided for indicating to the bystander the amount registered in the machine. The mechanism shown in the present application for accomplishing this function forms no part of the present invention and will be referred to only generally. As shown in Fig. 3 the rear end of each key is provided with a flat bearing surface underlying the stem of its related tablet indicator so as to lift it into view.

100 As best shown in Fig. 2 the amount indicators 40 related to the different denominational orders are arranged in groups and are suitably guided in the frame 23 to prevent 105 interference with each other. Since the amount keys extend transversely of the machine and the indicators are arranged in aligned groups the stem of each indicator is 110 offset transversely at its lower end so as to co-operate with its related key. No indicator has been provided for the "No sale" key 115 since this key is operated alone and the absence of any amount indication will show that 120 a "cash" transaction has not been performed which, of course, is equivalent to a "no sale" operation.

125 In order to hold the indicator which has been raised by the depression of a key in its elevated position so that the indication made thereby will be visible until another item is entered in the machine, each indicator is provided with a rearward extending lug 62 co-operating with a wing plate 63. The 130

function of the wing plate 63 is to release the previously raised indicator and retain the newly raised indicator in its elevated position.

It is desirable, of course, in machines of this class to provide a flash or guard for the indicating tablets to prevent them from becoming visible during an operation of the machine and until after the registration has been completed. As shown in Fig. 2 the flash 65 is of box formation and extends around the amount indicators. The flash is supported in position at its opposite ends by means of slides 66 which are guided at the sides of the back frame 23 so as to be reciprocally movable. As is best shown in Fig. 7 the lower portion of the slide 66 which extends forwardly is bifurcated at 67 to engage the flange of the key coupler. By this means the operation or elevation of the key coupler will also raise the slides 66 and the guard or flash will remain in this position to conceal the indicators as long as the coupler remains elevated.

25 *Date printing wheels and associated setting devices*

It is desirable that when the total amount of the sales and other information is printed upon a record bearing material that some means be provided to designate the day to which the information pertains or in some cases to show that it relates to the end of some arbitrary period.

For this reason the present register includes a series of date setting devices in the form of adjustable wheels 68, (Figs. 1, 2, 3, 5 and 9) which project through an aperture formed in the cabinet 30, but which are normally protected against improper manipulation by means of the hinged cover 32 previously referred to. The date setting wheels 68 which are adjustable so as to set the type wheels for printing the month, as well as the days of the month, are mounted upon a shaft 69 which is fastened at its extreme ends to the intermediate frames 25 and 26. Each adjusting wheel 68 has integral therewith a pinion adapted to mesh with the teeth of a co-operating pinion 70 which is loosely mounted upon a stub shaft attached to the side frame 26. The intermediate pinions 70 likewise mesh with the pinions of printing wheels 71 formed with raised characters and which are loosely mounted upon a shaft 72 passing between the intermediate frames 25 and 26. In order to hold the type wheels in their adjusted positions there is provided a series of spring-pressed aligning pawls 73 (Fig. 5) of the usual type and well known in the art.

By this means the date printing wheels 71 may be adjusted to any position so as to print the desired date upon the record bearing material when the printing mechanism is operated.

Consecutive numbering counters and operating devices

The illustrative machine is provided with a series of consecutive numbering counters which are adapted to register the total number of times that the machine has been operated, the number of times that the "No sale" key has been operated, and the number of resetting operations which have been performed. Since the first mentioned counter 70 operates each time that the machine is operated and the "no sale" counter registers the number of times that its associated key has been operated, the difference between the amounts registered on these special counters 75 will indicate the number of cash transactions performed during a certain period.

The special counters are of the multiple pawl, deep notch transfer type, well known in the art and described in many patents, one of which is the patent to Thomas Carney, #876,295 dated Jan. 7, 1908 and they are all mounted in one line on the shaft 72 which, as before mentioned, supports the dating type 85 wheels.

The "no sale" counter comprises three wheels 74 (Figs. 2 and 5) the peripheries of which are formed with raised printing characters and these wheels have attached thereto ratchet wheels co-operating with a multi-prong actuating pawl 75. (Fig. 3). The actuating pawl 75 is spring-pressed and pivotally mounted, by means of a pin 76, in a bail 77 loosely mounted upon the shaft 72 which carries all the consecutive numbering and dating wheels. The bail 77 has attached thereto a pin 78 co-operating with an arm 79 rigidly secured to a shaft 80. As is best shown in Fig. 2 the shaft 80 passes through the frame 25 and is journaled in the side frame 21 and has attached at its left end a second arm 81 (see Fig. 4 also) which is connected to the "No sale" key 33 by means of a link 82. From this it will be readily understood that when the "No sale" key is operated the shaft 80 will be rocked and by means of the pin and slot connection to the operating bail 77 and the actuating pawl 75 a unit will be added to the special counter.

As shown in Fig. 5 in order to accommodate a larger registration the "customer" counter which indicates the total number of operations of the machine is formed of four printing wheels 83 which co-operate with a multi-prong pawl carried by a bail 84 which are similar to the bail and pawl previously described in connection with the "no sale" counter. The bail 84 has attached thereto a pin 85 (Fig. 10) co-operating with a slot 120 formed in a bell-crank 86 loose upon the shaft 80. The lower end of the bell-crank 86 is connected by means of a pin and slot to a second bell-crank 87 loosely mounted upon the shaft 49 and bifurcated at its ex- 125 130

treme end to co-operate with an eccentrically mounted disk 88 fast to the rotation shaft 43.

From the above it will be evident that when the shaft 43 is rotated by means of an operation of a key the bell-crank 87 will be rocked and through the co-operating bell-crank 86 rock the bail 84 and through the actuating pawl insert a unit in the "customer" counter.

The counter on the left of the "customer" counter (Fig. 5) is known as the "reset" counter and it is provided for the purpose of registering the number of times that the resetting operation has been performed. As is shown in Fig. 5 the bail 89 which is associated with the "reset" counter wheels 90 is provided with a laterally extending lug 91 which is in the path of the pin 85 attached to the bail 84 associated with the "customer" counter. The bail 89 has attached thereto a laterally extending pin 92 which, as shown in Figs. 2 and 7, is in the plane of an arm 93 loose upon the shaft 80. The rearward portion of the arm 93 is connected by means of a link 94 to a resetting lever 95 loosely mounted upon the shaft 49. Fig. 7 shows the resetting lever 95 in its normal position and from an inspection of this view it will be seen that when the resetting lever 95 is forced rearwardly to perform a resetting operation as will be hereinafter described in detail, the arm 93 will be rocked upwardly to the position shown in Figs. 6 and 8 wherein it will be noticed that the pin 92 and bail 89 have been forced upwardly and forwardly but during this movement of the bail and actuating pawl the pawl was merely slipped idly over the ratchet wheels. It is obvious, of course, that the resetting lever can be operated as many times as desired without disturbing the bail 89 after it has once been adjusted to the position shown in Figs. 6 and 8.

However, when the machine is subsequently conditioned for an item entering operation and a key is depressed the "customer" counter will be operated in the usual manner. Since the bail 89 associated with the resetting counter has been forced upwardly and forwardly to bring it in line with the bails associated with the two remaining special counters, the pin 85 (Fig. 6) on the "customer" counter will contact with the lug 91 and force the bail 89 downwardly to its normal position and thereby add a unit to the "reset" counter. It will be clear, therefore, that the resetting lever merely cocks the operating means and that the unit is only entered whenever the machine is subsequently operated.

In order to hold the pawl operating means in any adjusted position the bail 89 has its rearward portion formed with notches 96 (Fig. 8) co-operating with a spring-pressed pawl 97. By means of this device the bail

89 will be held in its adjusted position and any accidental movement is prevented.

Printing mechanism

In cash registers of the class shown and described the total of the sales registered and other information is usually obtained by reading the amount standing upon the totalizer elements and other registering devices. It is preferable, however, to have this information printed upon a record bearing material as it then forms a permanent and unchangeable record which may be referred to at any desired time. For this reason the illustrative machine is provided with a simple and effective printing mechanism for printing the desired information upon a strip of paper.

In general the printing mechanism comprises a printing frame which is pivotally mounted and adapted to be manually swung about its pivot by the use of a knob or key to carry a pair of impression elements against the two lines of printing type already described. This frame is normally spring held in its outward position and is provided with suitable inking devices and means for carrying and guiding a record strip. As has already been explained the locked cover 32 normally conceals and prevents access to the printing mechanism. The details of construction of the various elements of the printer will now be described.

Referring to Fig. 12 it will be noted that the printing frame comprises a plate 100 integral with which are two side plates 98 and 99 the lower ends of which are apertured to receive the shaft 28 (Figs. 4 and 9). All of the associated printing members are carried by the frame just referred to and in order to prevent lateral movement of the printing mechanism the bar 24 is provided with rearwardly extending projections 101 (Figs. 2, 4 and 9) between which the lower end of the printer is positioned. Journalled in the side plates 98 and 99 at their upper portions is a shaft 102 (Figs. 11 and 12) forming the pivotal point of a platen 103 (Fig. 15) provided with two parallel rubber impression blocks 104. In order to retain the shaft 102 in the proper position there is provided a set screw 105 mounted in the platen 103 and adapted to contact with a groove in the shaft 102, and since the platen is prevented from any appreciable lateral movement by the side plates the shaft is likewise retained in position.

The ribbon supporting plates are comprised by two parallel plates 106 and 107 which are attached to each other by suitable means such as bent-over lugs 1061 (Fig. 13). The ribbon supporting plate 107 has attached thereto, by means of rivets 108 a pair of plates 109 fitting between the side plates 98 and 99 and the sides of the platen 103 substantially

- at right angles to the plate 107 and they are formed with elongated slots 110 (Fig. 14) to receive the platen supporting shaft 102. Springs 111 extend between projections on the plates 109 and the base of sockets 112 (Fig. 15) formed in the platen 103. By means of the four springs 111 the ribbon supporting plates 106 and 107 will be forced away from the rear face of the platen to the position shown in Fig. 11 wherein it will be noted that there is normally a considerable separation between these two elements thus facilitating the insertion of a paper strip in a manner which will be described hereinafter in detail.
- 10 15 It will also be noted from an inspection of this view (as well as Figs. 13 and 14) that the supporting plates 106 and 107 are suitably bent so as to form channels 113 located just over the impression blocks 104 for the 20 reception of a ribbon carrying frame or plate 115 and that both are apertured at 1062 so as not to interfere with the printing action when the printing frame is rocked.
- 25 The inking ribbon 114 comprises a narrow strip of ribbon, (Figs. 16 and 17) and is held or fixed in a frame 115 apertured at 1151 and which is formed by bending so as to grip the ribbon. This construction permits the detachment of an old ribbon from the printer 30 and the insertion of a new one without touching the moistened ribbon. There is a ribbon frame for each printing line so that they can be removed or replaced independently of each other. When it is desired not to print the information from a certain line of type this can 35 readily be done by removing the associated printing ribbon.
- 40 Referring to Fig. 11 it will be noted that the ribbon supporting plate 107 extends upwardly as well as downwardly and is curved so as to suitably guide the paper when it is inserted in the printing frame. The plate 107 also extends laterally to a width greater than 45 the side plates 98 and 99 and is bent at 1071 and 1072, the guard plates thus formed being adapted to cover at times the ribbon receiving apertures in the cover 31', for a reason which will be explained hereinafter.
- 50 Also extending between the side plates 98 and 99 is a curved plate 1152 (Figs. 3, 4 and 11) which is securely held in place by means of lugs 116 projecting through slots formed in the side plates and this curved plate serves 55 as a support and guide for the record material. It will be noted that the upper end of the fixed curved plate 1152 contacts with the lower rear edge of the pivoted platen 103 thereby limiting the rocking movement of the 60 platen 103 under the influence of the upper springs 111 in a clockwise direction as viewed in Fig. 11 while a lug 1000 integral with the plate 100 will hold the platen against a counter-clockwise movement if the lower springs 65 111 urge it in this direction.

As is best shown in Fig. 11 the paper strip is drawn from a roll 117 which rests upon the curved plate 1152 the roll being held in the proper position by means of lateral springs 118 (Fig. 12). The end of the paper strip is inserted between the plates 107 and 1152 which guide it over the rear face of the platen 103 after which it will be guided by the upper curved portion of the plate 107 so that it passes forwardly under a plate 119 which is riveted or otherwise secured to the side plates 98 and 99 and is formed at its extreme forward edge with serrations 120 adapted to facilitate the tearing of a section of a record strip from the rest of the roll. From an inspection of Fig. 12 it will be noted that the plate 100 is cut away at 121 so as to permit the insertion of a finger to draw the upper portion of the record strip outwardly before detaching a section of it from the rest 35 of the roll.

The relation of the printing devices to the cabinet cover is best shown in Fig. 1 wherein it will be noted that the cover 31' is apertured at its lower end at 122 to receive the roll of paper and is also apertured at 121' in line with opening 121 of plate 100 to permit the insertion of a finger to draw out the printed record strip. The side portions of the cover 31' are provided with four elongated apertures 123, two of which are shown in Fig. 1 and the other two in Fig. 9 and which are provided for the purpose of permitting a new ribbon frame to be inserted in the printer when the printer is in its normal position. When the printing mechanism is in its normal or raised position and it is desired to insert a new ribbon frame, the latter is merely inserted in the aperture 123 and by forcing it laterally the old frame will be ejected sufficiently to permit its withdrawal by the fingers so that the printer may accommodate and receive the new ribbon frame.

In some instances it would be of a particular advantage to persons who are permitted to obtain the printed totals from the machine to fraudulently manipulate the totalizer elements if that could be done so as to indicate a total less than that actually received. In order to guard against such a misoperation the printing mechanism is so constructed and provided with shields as to prevent the insertion of an instrument in the various apertures in the cabinet.

One way in which it might be possible to manipulate the printing wheels if no protective means were provided would be to withdraw one of the ribbon frames and insert a wire or some other instrument in one of the apertures 123 in the side of cover 31' and through the apertures 1062 until the wire strikes one of the totalizer elements in such a manner as to rotate it fraudulently. It is evident that this misoperation would be facilitated if the platen were swung rear-

wardly and close to the printing type as in a printing operation.

It is in this connection that plate 107 is bent laterally to form side plates 1071 and 1072 which fit close against the sides of the cover 31' for the printer as before explained. It will be understood that whenever the printer frame is moved toward the type wheels the apertures 123 will be covered by means of the plates 1071 and 1072.

In order to retain the printer in its forward or normal position the side plate 99 has attached thereto by means of a lug 124 (Figs. 9 and 12) a bell-crank 125 loosely mounted upon the pivotal shaft 28 of the printer. The tension in the spring 126 attached to the horizontal arm of the bell-crank normally retains the printing devices in the position shown in Fig. 9.

In order to prevent any lateral movement of the shaft 28 after it has been placed in its proper position one end of the shaft is provided with a groove 281 (Fig. 12). The bell-crank is provided with an irregular shaped aperture 1251 (Fig. 9) which is constricted to the diameter of the shaft 28 at its grooved portion, but sufficiently large to receive the shaft 28. It will be clear that when the shaft 28 is inserted and shifted laterally the spring 126 will force the lever to cooperate with the groove in the shaft and rigidly hold the latter in place.

In order to permit the printing mechanism to be forced rearwardly so as to take a printing impression from the adjusted type carriers there is provided a button 127 which as shown in Fig. 3 is slidably mounted in the cover 31' and has its rearward portion contacting with the plate 100. Each special counter has adjacently mounted a special printing member 128 (Figs. 5 and 27) loosely mounted on the shaft 72 carrying indicia which designate the counter with which it is associated. In order to hold the blocks rigid the lower end of each is apertured to receive a rod 1281 journalled in the intermediate frames 25 and 26. The totalizer 55 also carries a type block 129 bearing the word "Total" which is in correspondence with the printing line of the totalizer elements.

Let it be assumed that the machine has been conditioned to permit total printing and that the record strip has been properly inserted and that the ribbon frames are also in their proper places. The printing button 127 if now depressed will force the printing devices rearwardly, tensioning the spring 126. As the printing frame is forced rearwardly towards the type the rear ribbon supporting plate 106 will contact with a forward projection 130 (Figs. 4 and 9) of the intermediate frames 25 and 26, thereby holding the ribbons and their supporting plates against movement. As the printing button

is depressed still further the side plates 98 and 99 will, through the shaft 102 continue to force the platen rearwardly compressing the springs 111. At substantially this point of the operation the lower impression block 70 104 will contact with the totalizer elements, thereby holding the lower portion of the platen rigid and forcing the platen to rock slightly counter-clockwise so as to permit the upper impression block to strike the 75 special counter printing elements with the result that the elements of the two printing lines are struck with equal force. It will be understood that the rubber platen blocks must act to force the paper against the ink- 80 ribbons and adjusted type. For the best results the button 127 should be depressed sharply and quickly with the thumb, so as to obtain a clear and legible print on the record strip. 85

After this has been accomplished the finger is inserted in the aperture provided for that purpose and the portion of the printed record strip is withdrawn and detached from the rest of the roll. 90

Referring now particularly to Fig. 18T there will be seen an example of printing adapted to be performed by the illustrative machine. The word "total" is printed adjacent the figures representing the total of cash sales for some particular period and parallel to this printing line is the information which is printed by the special counters and the date printing wheels. After the resetting operation has been performed by the means which will next be described, the printing devices are again operated so as to furnish the proof that the desired registering elements again stand at zero. The proof of reset (Fig. 18Z) can be printed on the same paper as the total if desired, by simply withdrawing sufficient paper out of the printer after total printing to insure that a fresh portion of the record strip stands over the previously zeroized registering wheels for 100 105 110 115 120 125 130 the printing of the proof.

Resetting devices

At the termination of a day's business or any arbitrary period it is desirable that the various registering elements be returned to zero prior to the registration of the sales to be accumulated during a subsequent period. To this end the illustrative machine is provided with a single lever which, when given a complete reciprocation will reset the various elements to their zero positions.

As best shown in Figs. 1 and 23 the resetting lever projects through and works in a slot formed in a portion of the cabinet 30 which is under the cover 32. The resetting segment 95 (Fig. 7) is loosely mounted upon the shaft 49 and is provided with a forward extension 131 formed with teeth meshing with the teeth of a gear 132 (Fig. 5) loose 130

upon a stub shaft 1331 rigidly secured to the side frame 25. The pinion 132 has attached at one side a mutilated pinion 133 meshing with a pinion 134 loosely mounted upon the shaft 72 which, it will be remembered, supports the consecutive numbering counter wheels. Also connected to the pinion 132 at the other side is a bent disk 135 which co-operates with a spool 136 pinned to the shaft 58 which, it will be remembered, supports the totalizer elements. Attached to the spool 136 is a pinion 142 which is normally out of the plane of the pinion 133 with which it is adapted to mesh at certain times.

15 From the above it will be evident that when the resetting segment rotates the gear 132, the pinion 133 and bent disk 135 will rotate as a unit. It will furthermore be noted from an inspection of Figs. 5 and 22, 20 that the pinion 134 has integral therewith a semi-annular ring 137 which co-operates with a lateral projection 138 integral with a collar 139 pinned to the shaft 72. Due to the normal relationship between the semi-annular 25 ring 137 and the lug 138, the pinion 134 can be given an idle movement before the semi-annular ring 137 contacts with the lug 138 to rotate the collar 139 and the shaft 72.

As is best shown in Figs. 20 and 21, each 30 of the totalizer elements 57 carries a pivoted pawl 140 which is spring-pressed against the shaft 58. The shaft 58 is provided with a series of notches 141 one for each wheel of the totalizer. When the wheels are turned 35 in the registering operations of the machine the pawls 140 will slip idly over the shaft 58, since it will be noted (Fig. 21) that the resetting pawls 140 are normally out of the path of the associated notches 141. However, 40 when the shaft 58 is shifted as will be explained, to bring the notches and pawls in co-operative relationship (Fig. 20) and when the shaft 58 itself is turned in the direction of the arrow shown in Fig. 20 the abrupt wall of 45 the notch will contact with the ends of the pawls 140 and pick up the totalizer elements in whatever position they may be standing at the beginning of the movement of the shaft and carry them around with it, so that a complete revolution of the shaft in such direction 50 will serve to reset the totalizer elements to zero or initial position. This method of resetting is well known in the art and is a common expedient found in cash registers.

55 The shaft 72 which carries the special counters is provided with a series of notches similar to those in shaft 58 and they are normally in the plane of the resetting pawls 60 carried by the registering elements associated with the "customer" and "no sale" counters so that this shaft need not be shifted laterally. The "reset" counter wheels 90 (Fig. 6) are not provided with any resetting pawls or associated notches in the supporting shaft 58 so

that when the shaft 72 is rotated as will hereinafter be described in detail, the "Reset" counter elements will not be restored to their zero positions, but will continue to accumulate units whenever the resetting lever and the 70 operating keys are operated alternately.

As will be noted in Fig. 5 the disk 135 is bent at an angle and the disk projects into a groove in a collar 136 secured to the totalizer shaft 58. It will be seen therefore, that when the disk 135 is rocked the bent portion will co-operate with the wall portions adjacent to the groove and shift the shaft 58 laterally. In order to permit the proper camming action of the bent portion of the disk 135 the collar 80 136 is cut away as shown at 136' in Fig. 24.

Assuming that the resetting lever is unlocked for operation it will be obvious that when the resetting lever 95 is moved from the position shown in Fig. 7 to the position shown 85 in Fig. 8, the teeth of the segmental rack carried by the lever 95 will rotate the pinion 132 and the bent disk 135 in a clockwise direction as shown in Fig. 7. Due to the co-operation of the said disk and the collar 136 the shaft 58 will be shifted to bring the pinion 142 carried by the shaft adjacent the collar, into mesh with the teeth of the mutilated pinion 133 and furthermore to bring the resetting pawls 140 and notches 141 into co-acting relationship. 90

During this time the gear 134 will have been moved counterclockwise as viewed in Fig. 22, until one end of the semi-annular ring 137 contacts with the lug 138 carried by the collar 139. At substantially the time that the pinions 142 and 133 are in engagement the annular ring 137 has been rocked sufficiently to contact with the lug 138 so that a further rearward movement of the resetting lever will, 100 through the train of mechanism rotate the shafts 58 and 72, the notches of which co-operate with the pick-up pawls 140 and restore the numeral elements to their zero positions. It may be noted that the wheels of the totalizer are restored by rotation in a direction opposite to that in which they are driven by the actuators, whereas the wheels of the special counter are restored through continuation of 110 positive rotation. 115

After the resetting lever has been forced rearward fully it is again returned to its normal position which will return the resetting shafts 58 and 72 backwardly without affecting the position of the registering elements, due to the formation of the notches with only one abrupt face and one face which is beveled to permit this idle return movement. It will be understood that at the beginning of the return movement of the reset lever there will be a lost motion between pinion 134 and shaft 72 until the element 137 engages the opposite face of lug 138, while toward the end of the return stroke shaft 58 will be laterally restored to normal. When the reset lever is at 120 125 130

its home position, the parts will again stand in the positions shown in Figs. 4 and 7.

Due to the fact that a considerable amount of friction exists between the sides of the bent 5 disk 135 and the co-operating walls of the slot in the collar 136, the disk has a tendency to rotate the shaft 58 before the latter has been shifted to mesh its pinion 142 with segment 133. For this reason it is desirable to 10 lock the shaft 58 against rotation while it is being shifted and to release it at substantially the time the "pick-up" pawls and the notches and related pinions 142 and 133 are in co-acting relationship. To this end there 15 is attached to the stub shaft 1331 by means of a set screw 144 or other suitable means, a collar 143 having riveted thereto an arm 145 suitably bent so as to form a lug 146. The lug 146 as shown in Figs. 5 and 7 normally co- 20 operates with lugs 147 and 148 which are formed as part of a member attached to a collar 149 fast to the shaft 58. It will be noted also that the lug 147 is shorter than the lug 148. Bearing in mind that the lug 146 is 25 fixed, it will be obvious that when the shaft 58 is shifted laterally by the means previously described the shorter lug 147 will be shifted until it clears the fixed lug 146. At this time the pinion 142 on the shaft 58 is in mesh with 30 the first tooth formed on the mutilated pinion 133 so that while shaft 58 has been locked against rotation during its lateral movement it is now unlocked so that a further rearward movement of the resetting lever 95 will ro- 35 tate the shaft 58 counter-clockwise and the lug 148 as viewed in Fig. 7 will move away from the fixed lug 146 until the lug 148 occupies the position in engagement with the opposite side of the fixed lug as shown in Fig. 40 8 where it has served as a stop for the resetting lever and correlated devices.

As the resetting lever is again drawn forwardly to its normal position it will rock the shaft 58 clockwise as viewed in Fig. 8 and 45 bring the parts back to the normal position shown in Figs. 5 and 7, the shaft being restored laterally after the lug 148 has engaged the lower edge of the fixed lug 146.

From an inspection of Figs. 5 and 25 it 50 will be noted that the mutilated pinion 133 is not provided with a full complement of teeth but has a portion 1332 which is concentric with respect to the stub shaft 1331. It will be evident that before the lug 147 clears the 55 lug 146 to unlock the shaft 58 the pinion 142 is shifted laterally sufficient so that the concentric portion 1332 of the pinion 133 co-operates with the teeth of the pinion 142 to align the pinion to insure that its teeth will 60 properly mesh with the first tooth of the pinion 133. It will also be clear that the concentric edge 1332 also acts as a geneva lock to hold the shaft 58 against rotation while it is being shifted laterally.

65 It is essential once the resetting operation

has been started that some means be provided to insure that a complete resetting operation will be effected. To this end there is attached to the mutilated pinion 133 a segment 150 (Fig. 6) provided with ratchet teeth 151 70 meshing with a spring urged pawl 152. From the above it will be obvious that once the resetting lever has been forced even partially rearwardly to reset the various elements it will be necessary to give the lever a full 75 stroke rearwardly and forwardly in order to bring the parts to normal again.

After the resetting operation has been performed the printing mechanism may again be operated to prove that the reset operation has 80 been performed correctly. Fig. 18Z shows an example of the proof of reset wherein it will be seen that all the registering elements have been zeroized with the exception of the "reset" counter wheels which still indicate 85 "2".

When the machine is subsequently operated at the beginning of another period the units wheel of the "Reset" counter will be turned to "3" which is the reset number for the sales 90 to be registered during the next period.

At this time it should also be pointed out that as best shown in Figs. 4, 7 and 8, the lug 146 is bent in an arc that is substantially concentric with respect to the totalized pivot 56. 95 When the shaft 58 is moved forwardly by means of the totalizer engaging mechanism the lugs 147 and 148 will move with it, but will not be interfered with by the stationary lug 146. This mechanism tends to hold the shaft 58 at all times and counteracts any tendency of the operated totalizer pinions to rotate the shaft due to the friction between the spring-pressed pawls and the periphery of the shaft.

Drawer release by an operation of the machine

In a machine of this type it is customary to provide a cash drawer which is released upon 110 each operation of the machine and ejected outwardly under the action of a spring to expose the same for the purpose of making change or receiving the money tendered. To this end the machine is provided with a cash drawer 154 (Fig. 1) suitably guided in a drawer base 155 and normally urged outwardly by the usual drawer spring 156. The drawer, however, is retained in its innermost position by a drawer catch 157 engaging a portion of the cash drawer and which is pivoted to a short shaft 158 journaled in a yoke-shaped frame 159 attached to the drawer base 155. At the other end of the shaft there is attached an arm 160 (Fig. 7) connected to a link 161 (Fig. 4) which carries a roller 162 co-operating with a cam 163 fast to the rotation shaft. The roller 162 is urged against the cam 163 by means of a spring 164.

When the shaft 43 is rotated by an opera-

tion of the keys, the cam 163 will elevate the link 161 and through the train of mechanism just described disengage the drawer catch from the cash drawer permitting the drawer 6 spring to eject the cash drawer. The profile of the cam 163 is such that the cash drawer will be ejected during the return stroke of the keys which is after the completion of the registering operation. It will also be noted that 10 the fulcrum of the drawer catch is substantially in the same horizontal plane as the top of the cash drawer, which permits of an easy release of the cash drawer without imposing a load upon the operating mechanism, as would 15 be the case if the drawer catch 157 was pivoted at the other side of the drawer spring and above the horizontal plane of the cash drawer.

20

Control lever

In the type of machine shown in the drawings it is a common expedient to provide means whereby the keys are locked against operation while the cash drawer is exposed 25 and thus the operator is forced to close the cash drawer at the end of each operation so as not to leave the money contained therein exposed between the operations of the machine. The purpose of such constructions is 30 also to compel the operator of the machine to make some record or indication before access to the money contained in the drawer may be had. In certain uses of the machines, it is desirable to disable the mechanism just 35 described so as to permit successive operations of the machine during rush hours without closing the cash drawer after each operation. Again, it is desirable at times to lock the operating keys irrespective of the position 40 of the cash drawer so as to prevent tampering by unauthorized persons.

To provide for these functions the mechanism embodied in the illustrative machine is placed under the control of a single lever located 45 under the hinged cover 32, and when the latter is securely locked access to the lever cannot be had except by persons having the key of the lock for the cover. The control lever is adapted to be shifted to any one of 50 three positions to accomplish a corresponding one of the functions above mentioned and it also has another position known as the "total" position which releases the cash drawer and conditions the entire machine for total printing and in some cases permits re-setting to be performed.

As is best shown in Fig. 4 the control lever 60 165 is loosely mounted upon the shaft 49 and is guided in its reciprocating movement by means of a slot 166 (Fig. 2) formed in a plate 167 riveted to the outside of the intermediate frame 25. The control lever 165 projects through a slot in the cabinet 30 (Figs. 1 and 23) which has attached thereto an index plate 66' which carries legends designating

the various positions of adjustment of the control lever. In order to align the control lever in its adjusted positions, there is provided an aligning lever 167' (Fig. 4) which is spring-pressed so as to urge a pin 168 carried thereby to engage one of a series of wedge-shaped notches 169 formed in the lower edge of a rearward extension 170 of the control lever.

It will be assumed that the control lever is 70 unlocked for operation by the means which will be hereinafter described, and that it has been moved to the "closed drawer" position (Fig. 4) which is the position that the lever takes so as to set the mechanism which requires the closing of the cash drawer before the keys can be subsequently operated. The mechanism for accomplishing this function will now be described in detail, reference being had particularly to Figs. 4, 7 and 8.

As is shown in these figures, there is loosely pivoted upon the shaft 29 previously mentioned a locking arm 171 which is provided with a shoulder 172 adapted to co-operate with the flange of the key coupler at certain times, and extends further downwardly so as to contact with the rear end of the cash drawer 154.

Also loosely mounted upon the shaft 29 is a second locking lever 173 which is also formed at its lower end with a shoulder 174 adapted to engage the flange of the key coupler and extends upwardly to form extension 175 formed with a slot 176. It will be noted that while the lever 171 and 173 are mounted independently of each other they are drawn together by means of a spring 178, the relative movement being limited by means of a stud 179 attached to the lever 173 contacting with the forward edge of the locking lever 171. It will be noted in Fig. 4 that the lower end of the spring 164, previously described in connection with the drawer release devices is connected to a pin 180 carried by the locking lever 171. By means of the flexible connection formed by spring 178 either locking lever can be moved independently of the other, but under certain conditions both are moved together as a unitary structure.

In Fig. 4 the co-operating parts are shown in the position they assume when the control lever is adjusted to the "Closed drawer" position with the cash drawer already returned thereby freeing the keys for subsequent operation. When the keys are again operated and the cash drawer released, it will be obvious that the lower end of the lever 171 will no longer contact with the cash drawer and that the tension normally existing in the spring 164 will rock the locking lever 171 counter-clockwise and due to the interconnecting spring 178 both levers 171 and 173 will move as a unitary structure bringing their respective shoulders over the flange of the key coupler, thereby locking the coupler.

and the keys against operation as long as the cash drawer remains open. However, when the cash drawer is forced inwardly the rear end of the cash drawer will contact with the 5 lower end of the lever 171 rocking both locking levers rearwardly to unlock the coupler and slightly tensioning the spring 164. The parts are then again in the position shown in Fig. 4 permitting of a subsequent operation 10 of the keys.

In order to disable the above described automatic locking mechanism for the keys, the control lever is moved one step rearwardly from the position shown in Fig. 4. As 15 shown in this figure the rearward extension 170 of the control lever 165 carries a pin 181 adapted to co-operate with the beveled edge 175 as well as with the slot 176 in extension 175 of the locking lever 173. When the 20 control lever 165 is moved rearwardly one step, the pin 181 will be brought to a position directly over the edge 175 of the extension 175 and positively hold the locking levers in the position shown in Fig. 4. Thus, 25 it will be obvious that when the machine is operated and the cash drawer is ejected so as to relieve the contact between the lever 171 and the rear end of the cash drawer the tension in the spring 164 cannot urge the levers to locking position as before since they 30 will be positively held back by means of the pin 181 contacting with the beveled edge of the extension 175 thus permitting the machine to be operated successively irrespec- 35 tive of the position of the cash drawer. It will be understood that the stud 179 carried by the lever 173 serves to hold back the lever 171.

At the close of a day's business it is desirable 40 to leave the cash register with the empty cash drawer exposed and the operating keys locked so as to prevent false registrations. At other times it is desirable to lock 45 both the keys and the cash drawer so as to prevent unauthorized persons from having access to the contents of the cash drawer by operating the keys. The present machine provides additional mechanism for accomplishing either of these purposes.

To perform these functions the control lever is moved two spaces from the position shown in Fig. 4 so that the foremost notch 169 co-operates with the pin 168 carried by the aligning lever 167 which coincides with 55 the position shown on the index plate designated as "Lock register". When it is desired to lock the machine as in the latter instance stated above, the control lever is moved to the "lock register" position, so that the pin 60 181 co-operates with the rearward wall of the slot 176 to positively move the locking lever 173 to bring its locking shoulder 174 over the flange of the key coupler. Due to the interconnecting spring 178 the locking lever 171 has a tendency to swing its shoul-

der 172 over the lip of the key coupler also but if the drawer is closed at this time the lever 171 will, of course, be held back. Now, when the control lever 165 is locked in this position, by the means which will be herein- 70 after described, the keys will be locked against operation and it will be impossible to obtain access to the contents of the cash drawer by operating the keys.

When the register is to be locked in the other manner, that is, with the cash drawer open, the cash drawer must previously be released either by an operation of the machine, or by the supplemental means which will be hereinafter described, and then the control lever must be moved to the "lock register" position. If, at any time, it is desired to return the cash drawer, this can be performed without disabling the locking means 75 since it will be obvious that the return of the cash drawer will merely force the lever 171 rearwardly and tension the spring 178 but will not affect the position of the locking lever 173 since it is positively held in locking position by the co-operation of the pin 181 80 with the rear wall of the slot 176.

The control lever 165 is capable of being moved to still another position known as the "total" position, and when the control lever is brought so as to correspond with this position as shown on the index plate 66', a number of functions are performed. These will be taken up under the next heading.

LOCKS AND INTERLOCKING MECHANISM

100

1. LOCKS

It is desirable whenever the control lever 165 is in any position but the "total" that the resetting lever and printing mechanism be locked against operation. In order to lock the printer against operation the side plate 98 of the printer is provided with a locking lug 182 (Fig. 4) adapted to co-operate with the locking edge 183 of a double armed member 184 attached to a shaft 185 which passes through the intermediate frames 25 and 26 and has attached at its other end a locking arm 186 (Fig. 9) provided with a locking edge 187 adapted to co-operate with the locking lug 124 previously referred to. From the above it will be quite clear that if an attempt should be made to move the printer by operating the button 127 it will normally be stopped by the lugs 124 and 182 110 contacting with the associated locking surfaces of the locking arms 186 and 184, respectively.

In order to lock the resetting lever 95 against operation whenever the control lever 165 is in any position except the "total" position, the following means is employed. The reset lever 95 has connected thereto a member 188 (Fig. 4) bifurcated to form an open slot 1901 at its forward end to engage the shaft 185 and, in addition, it is provided with a 125 130

notch 189 (Fig. 4) co-operating with a stud 190 on the rearward extension of the pivoted member 184. The control lever 165 has also attached thereto a member 191 which is provided with an inclined slot 192 also embracing the shaft 185 and, in addition, has a portion of its lower edge 193 substantially parallel to the incline of the slot 192. As shown in Fig. 4, the edge 193 contacts with the pin 190.

From the above it will be evident that if an attempt is made to move the resetting lever 95 rearwardly from the position shown in Fig. 4 while the control lever is in the "closed-drawer" position, it will be prevented by the contacting of the pin 190 against the forward wall of the slot 189. If there is any tendency of the wall of the slot to cam the pin 190 upwardly out of the slot 189, it will be overcome by the contact of the pin 190 against the inclined edge 193. If the control lever is moved to any of the next two positions "open drawer" or "locked register" the bevel edge 193 will still contact with the pin 190 locking the resetting lever against rearward movement.

As has been premised hereinbefore the printing mechanism and the resetting lever are unlocked for operation whenever the control lever 165 is directly moved to the "total" position and just how this is performed will now be described. As will be noted in Fig. 4, the member 191 is provided with a forward extension 194 co-operating with a pin 195 carried by the locking element 184. When the control lever 165 is moved forwardly one step from the position shown in Fig. 4 to the position shown in Fig. 7 the member 191 will be moved forwardly and downwardly due to the inclination of the slot 192 so that the projection 194 will force the stud 195 downwardly and thereby rocking the locking member 184 in a clockwise direction. This will bring the notches 196 (Fig. 9) and 197 formed in their respective locking arms 186 and 184 into registry with the locking lugs 124 and 182, respectively. The printing devices can now be moved rearwardly to effect a printing operation since there will be no interference with the studs 124 and 182.

When the extension 194 co-operates with the stud 195 to rock the locking arm 184 clockwise it forces the pin 190 upwardly out of the slot 189 thereby unlocking the resetting lever for operation.

Whenever the control lever is brought to the position shown in Fig. 7, an integral extension 1651 of the control lever will contact with a stud 1652 attached to the link 161 so as to operate the drawer catch 157 to release the cash drawer.

Summarizing the above, whenever the control lever is moved to the "total" position the cash drawer will be released and the

printer frame and resetting lever will be unlocked for operation.

2. INTERLOCKING DEVICES

The mechanism as thus far described is substantially complete and practically operative but some devices, which may be called precautionary devices are desired to prevent any possible mis-operations of the machine.

Owing to the prejudice on the part of persons operating cash registers they are subjected to the severest strains in an effort to make them break down or print incorrect amounts. While the present machine has locking devices, such as described in the preceding section which merely unlock the various manipulative devices for operation, it includes co-ordinated interlocking devices which prevent the simultaneous operation of two or more of them. As shown in the drawings the mechanism for effecting the above is simple in construction but it is very effective in its performance.

When the control lever 165 is drawn forwardly from the position shown in Fig. 4 to the position shown in Fig. 7, it will be seen that a stud 198 carried by a projecting member 1991 integral with the control lever will co-operate with a cam surface 177 formed on the underside of the upper end of the locking lever 173. This will rock the locking lever 173 counter-clockwise to the position shown in Figs. 7 and 8 in the first of which it will be noted that both locking levers now have their respective shoulders 100 engaging the flange of the key coupler, locking the registering keys against operation as long as the control lever remains in the "total" position. It will be clear, therefore, so long as the control lever is in the "total" position, even though the drawer may be returned to its innermost position, and held there by the operator it will not effect the unlocking of the keys since the locking lever 171 will merely be moved rearward tensioning the spring 178 without shifting the lever 173. As has been explained hereinbefore, the resetting lever and the printing mechanism are normally locked but are unlocked for operation when the control lever is in the "total" position. The means just referred to will therefore prevent the simultaneous operation of the operating keys and either the printing mechanism or the resetting lever.

It is desirable while printing is being performed that the resetting lever and the control lever be locked against operation. It will be evident that when the printer is moved rearwardly from the position shown in Fig. 7 the engagement of the lug 182 in the slot 197 will hold the locking member 184 rigidly and if it is attempted to move the control lever out of the "total" position it will be blocked by a bevel edge 199 formed on the

underside of the member 191 engaging the stud 190. In a similar manner, when the printer is moved to effect printing, the resetting lever 95 will also be locked against movement since a corresponding beveled edge 200 on the member 188 will co-operate with the stud 190 carried by the rigidly held locking member 184. Since the control lever 165 is thus locked against any movement it will, of course, be impossible to move it out of the "total" position to unlock the operating keys as long as the printer is in the printing position.

While the resetting operation is being performed it is desirable to lock the printing mechanism and the control lever against movement from the position shown in Fig. 7. As the resetting lever is moved from the position shown in Fig. 7 to the position shown in Fig. 8 the beveled edge 200 on the member 188 which is attached to the resetting lever 95 will cam the pin 190 upwardly thereby rocking the locking member 184 clockwise to bring a locking edge 201 formed just above the slot 197 on the member 184 in front of the stud 182. In a similar manner referring to Fig. 9 the locking arm 186 will be rocked counter-clockwise to bring a locking surface 201 in front of the locking lug 124. This will positively lock the printer against operation as long as the resetting lever is displaced from its normal position.

When the locking member 184 was rocked clockwise as shown in Fig. 8, by movement of the resetting lever it brought the pin 190 in back of a shoulder 202 formed on the member 191 which is attached to the control lever. This locks the control lever 165 in the "total" position (shown in Fig. 8) thereby preventing it from being moved to unlock the operating keys.

When the resetting lever is moved forwardly from the position shown in Fig. 8 to the position shown in Fig. 7, an extension 235 of the member 188 will contact with the stud 195 and rock the member 184 counter-clockwise bringing the parts to the position shown in Fig. 7, wherein the control lever and printer are again unlocked for operation.

From the foregoing description it will be seen that provision is made for preventing the simultaneous operation of the resetting lever and the amount keys. However, in view of the possibility of the distortion of some of the parts by forcing them in spite of the restraint of the interlocking devices which might give a dishonest employee an opportunity to mis-operate the machine, with the resultant damage to parts and perhaps a wrong registration, a second interlock has been added as a precautionary measure.

For this purpose, the resetting lever 95 is provided with a rearward projection 203 which has an edge 204 concentric with respect

to the shaft 49 and another edge 205 which is concentric with respect to the rotation shaft 43. The projection 203 is in the plane of the box cam 61 previously referred to, the box cam being provided with a milled slot 206 normally concentric with shaft 49 and adapted to receive the projection 203 at certain times. If it should be possible to force the control lever forwardly against the restraint of lever 175 to unlock the resetting lever, after the keys have previously been partly depressed, movement of the resetting lever 95 will still be prevented by the edge 205 of the projection 203 contacting with the periphery of the partially rotated cam 61. While this mechanism is very simple it provides an adequate preventive for the mis-operation just referred to.

It will also be noted that if the resetting lever should be partially shifted as shown in Fig. 8 the projection 203 will cooperate with the milled slot 206 positively locking the keys against operation. This serves as an additional precaution for preventing the simultaneous operation of the keys and the resetting lever if the other interlocking device should be so strained as to fail to operate.

Control lock—single lock register

During the description which has previously been given, reference has been made to a hinged cover 32 which conceals and covers the various control levers and printing button. It is, of course, desirable to have the cover locked and to this end the illustrative embodiment is provided with a single lock which releases the cover to obtain access to the different manipulative devices. As shown in Fig. 1 the lock projects through the cabinet 30 and is attached as shown in Figs 2 and 9 to a plate 206 attached to the rear frame 23. The barrel of the lock has attached thereto a cam 207 co-operating with pins 208 carried by a shiftable shaft 209 (shown in Figs. 2, 4, 7 and 8) which is provided with slots 212 and 213 (Fig. 26). The upper edge of the control lever is scalloped to form three semi-circular notches 211 which are associated with the three rearmost positions of the control lever while the resetting lever has but a single semi-circular notch 224 (Fig. 8). The slots 212 and 213 formed in the shiftable shaft are normally out of the plane of the control lever 165 and reset lever 95, respectively. In order to guide the shaft 209 in its reciprocating movements and prevent it from rotating in the supporting plates 25 and 26 there is attached to the shaft an arm 236 (Figs. 2 and 9) carrying a pin 237 working in an aperture in the side frame 26.

Co-operating with a notch in the shiftable shaft 209 is a bell-crank 214, one end of which projects into an aperture 215 (Fig. 9) formed in a sliding plate 216 guided by studs 217 carried by the side frame 26. The shiftable

plate 216 is provided with an extension 218 which passes through a slot in the cabinet 30 and rests quite closely against the right side of the printer cover 31'. In order to hold the cover 32 latched the said cover is provided with a catch 219 (Figs. 1 and 9) which is connected to a similar catch (not shown) at the opposite side of the cover by a yoke 220. The lid catches 219 are urged by a spring 221 (Fig. 9) so as to engage studs 221' carried by the printer cover 31'. Integral with the right hand catch 219 is a member 222 which is adapted to co-operate with the extension 218 previously referred to.

To summarize the operation of the above, it will be evident that when a key is inserted in the Yale lock and the bolt turned in a clockwise direction as viewed in Fig. 2 the action of the cam 207 upon the studs 208 will be such so as to shift the shaft 209 to the left as viewed in Fig. 2. This will rock the bell-crank 214 counter-clockwise so as to draw the plate 216 rearwardly and through the extension 218 operate the yoke 221 to disengage both catches 219 from their associated studs 221'. The cover 32 is now unlocked and it may be held elevated in any position desired by means which will hereinafter be described. At the time the shaft 209 was being shifted to release the cover 32, it brought the notch 212 in the plane of the control lever 165 permitting it to be moved to any position. At the same time the notch 213 will register with the notch 224 in the resetting lever 95 thus unlocking it for operation and permitting it to be operated after the control lever has been shifted to the "total" position. It will be clear therefore, that the control lever can be locked in any of the three rearmost positions by again moving the shaft in the reverse direction through the rotation of the bolt of the lock so that one of the semi-circular notches in the lever co-operates with the periphery of the shaft 209. It will be noted that the control lever is not provided with any semi-circular notch 211 corresponding to the "total" position of the lever and it can not, therefore, be locked in this position. Since the resetting lever is provided with only one semi-circular notch 224 this lever can only be locked in its normal position and the lock can not be turned back to normal if the resetting lever is shifted away from normal.

55 Control lock—auditor's machine

In the description which has been previously given reference has been made to a single lock which controls the release of the cover and simultaneously unlocks the various manipulative devices so that one person can have entire control over the cash register. While this is desirable and convenient in some classes of business it is not entirely suitable for other classes. For example, a large number of corporations, such as, grocers, gasoline

vending companies, shoe manufacturers and the like have organized throughout the United States or a given territory a number of retail stores known as "chain" stores and the management of them is directly controlled by a manager in charge of each store.

The manager forwards daily reports to the head office and these reports are used to deduce the amount of business transacted by each store. Periodically an auditor visits each store to check the amount of sales for the month against the cash received, after which the auditor resets the totalizing device so as to accumulate the sales relating to a subsequent period.

It is, therefore, desirable that while the manager has control over the control lever and printing mechanism he should not have any control over the resetting lever. The mechanism shown in the illustrative machine permits the auditor to have control over all the devices accessible to the manager, and in addition, allows him to control the unlocking of the resetting lever. The mechanism for accomplishing the above will now be described in detail, reference being had particularly to Fig. 26.

In this type of machine two locks are provided (Fig. 26) reference character 207 denoting the manager's lock which carries a cam 207 working on the studs 208. When the manager inserts his key and rotates the bolt of the lock in a clockwise direction (as viewed in Fig. 26) the shaft 209 will be shifted laterally to the right bringing a notch 252 to register with the notches 211 formed in the control lever 165. The bell-crank 214 is also rocked in a clockwise direction and will serve to shift the plate 216 (Fig. 9) forwardly until the extension 218 contacts with a cam edge 223 of the lid catch 219 camming the catch rearwardly and thereby unlocking the lid 32 in the usual manner.

After the cover 32 has been elevated the control lever may be shifted to any of its desired positions or if the manager so desires to the "total" position to print totals. However, it is to be noted at this point that since the shaft 209 is shifted to the right the notch 213 which is provided to unlock the resetting lever will be moved further away from the plane of the lever, and since the notch 224 co-operates with the periphery of the shaft 209 the resetting lever will be locked against operation.

At the end of an arbitrary period when the auditor visits the store and desires to reset the machine he inserts his key in a supplemental lock 225 which is likewise provided with a cam 226 co-operating with the stud 208, previously referred to, and a stud 227. When the auditor rotates his key in a clockwise direction on account of the position of the cam 226, it will shift the shaft 209 to the left as viewed in Fig. 26. This will rock the bell-crank 214 counter-clockwise and

shift the slide 216 to the rear and through the co-action of the extensions 218 and 222 (Fig. 9) will operate the cover catches to release the cover 32. This will permit the auditor to lift the cover 32 and shift the control lever to the "total" position. When the shaft 209 was shifted to the left it brought the notch 213 in said shaft to register with the notch 224 formed in the rear end of the reset lever, thereby unlocking the latter for operation. It will be seen, therefore, that the auditor has control over all the manipulative devices that the manager has and, furthermore, is able to unlock the resetting lever for operation.

In Fig. 2 it will be noted that, if no means were provided to prevent it in a single lock machine the rod 209 might become accidentally shifted to the right since cam 207 in its normal position will not interfere with the studs 208 and thus the lock might be prevented from functioning due to the two shoulders on the cam plate engaging the pair of studs 208. In order to prevent such improper shifting of the shaft the guide pin 237 (Fig. 2) carried by the arm 236 is provided with a slot 240 in which is inserted a clip which locks the shaft 209 against any movement to the right.

While the above is an example of one use of the register provided with multiple locks it will be readily understood that the same mechanism can be adapted for any other analogous business and it is not intended to confine or limit its application to the line of business in connection with which it is described herein.

Lid retainer

The cover 32 which covers the manipulative devices referred to has considerable weight and if it should fall accidentally upon the hand injurious consequences might result. For this reason the illustrative machine is provided with a device for frictionally retaining the cover in any position to which it is adjusted. To this end there is attached to the inside of the cover 32 an arm 229 (Fig. 9) which passes through a slot in the cabinet 30 and passes between a fixed stud 230 mounted on the frame 26 and a stud 231 attached to a bell-crank 232 mounted on the stud 217 and to which the other end of the spring 126 previously mentioned is attached. Due to the friction between the rearward edge of the arm 229 and the periphery of the stud 231 the cover will be held in any desired position and due to the shape of the arm 229 the friction for holding the lid will be greatest when most needed, i. e. when the lid is nearer horizontal. Upward movement of the cover will be limited by a shoulder 233 contacting with the stud 231.

Audible signal

It is desirable in this class of machine to give an audible signal as by the ringing of a bell whenever the machine is operated and it is furthermore desirable at times to disable the bell ringing device. This mechanism forms no part of the present invention and will be merely described in a general way. Referring particularly to Figs. 2 and 9 it will be seen that bell 241 is in the path of a spring operated bell hammer 242 having a tail portion 243 adapted to be engaged by a plate 244 carried by a member 245. The member 245 is secured to the rotation shaft 43 so that rotation of this shaft will through the plate rock the bell hammer 242 clockwise against the action of its spring until the plate clears the tail 243 permitting the hammer to strike the bell.

In order to disable the bell sounding device there is provided a lever 2441 which is connected to an arm 245 by means of a yoke 246 said arm being provided with a lug 247 adapted to cooperate with a cam edge 248 on the bell hammer. When the lever is forced rearwardly the tail 243 will be cammed out of the range of the tail 244 and held there by the engagement of the lug 247 with a shoulder 250. As shown in Fig. 1 the lever 2441 is close to the side of the cover 31' and is adapted to be locked against improper manipulation by means of the cover 32.

General summary of operation

The nature of the improved mechanism is such that in order to make the foregoing description as clear as possible, it was necessary to state the operation considerably in detail as an incident to explaining the various features of construction. A complete restatement here of the operation is therefore believed to be unnecessary. However, a resume of the general operation of the machine will now be given to co-ordinate the operation and functions of the various parts which have been described in detail.

Let it be assumed that the machine is of the type equipped with a single proprietor's lock 207 and that the proprietor uses the machine for accumulating the sales of a day. The machine is generally left at the close of a day with the cash drawer 154 in its exposed position and the control lever 165 adjusted to the "lock register" position. The proprietor inserts his key in his lock and rotates it with the cam 207 clockwise (Fig. 2) unlatching the cover 32 and bringing the notches 212 and 213 (Fig. 26) in the plane of the control lever 165 and resetting lever 95, respectively. The cover is then elevated and the control lever is shifted to the "closed drawer" position (as shown in Fig. 4) which is the usual condition under which the machine is operated. The lid is then closed and the key is withdrawn.

from the lock leaving the machine ready for the day's business.

To enter the first cash transaction, which will be assumed to amount to \$1.65, the appropriate keys in the dollars, dimes and penny banks are depressed so that the notches in the rear ends of the keys engage the flange 37 of the key coupler 36 and through the rotation shaft 43 and the link 59 (Fig. 6) the 5 totalizer elements 57 are drawn into engagement with the differentially operated racks 54 (Fig. 3). As the proper keys are depressed the associated rollers 47 will work in the associated cam slots 52 formed in the 10 plates 48 of the differential frames related to the three banks. The frames 50 will each be differentially operated so as to move the racks 54 an amount commensurate with the 15 depressed keys. Since the totalizer pinions 58' are drawn into mesh with the actuating racks 54 before the racks have moved, the operated racks will move the pinions 58' differentially so that the amount \$1.65 will be 20 added on the totalizer elements 57. On the 25 return of the keys to normal the totalizer pinions will be disengaged from the racks so that the return movement of the latter will not affect the amount registered.

When the keys are returned to their normal positions, the cam 163 (Fig. 4) will, in addition, elevate the link 161 and operate the drawer catch 157 (Fig. 1) to permit the spring 156 to eject the cash drawer 154. The rotation shaft 43 will also operate the bell hammer 242 (Fig. 2) so as to ring the bell 241 to inform the bystander that the machine has been operated.

During the depression of the keys the appropriate tablet indicators 40 will be elevated by their related keys and at the same time the flash 65 will be elevated by means of the slides 66 connected (as shown in Fig. 7) to the flange of the key coupler 36. During the 40 return movement of the flash by the restoration of the key coupler and the keys the wing plate 63 (Fig. 3) co-operating with the lugs 62 of the elevated tablets 40 will hold them in their raised positions and when the flash 45 65 descends the amount indicators will indicate the amount of the transaction.

During the rotation of the shaft 43 the eccentrically mounted disk 88 (Fig. 10) will operate the bell-cranks 87 and 86 so as to rock 50 the bail 84 to add a unit in the units wheel 83 of the "customer" counter. During the 55 first transaction the pin 85 (Fig. 5) carried by the bail 84 associated with the "customer" counter will co-operate with the extension 91 60 of the bail 89, associated with the "reset" counter which was cocked forward on the previous resetting operation and will thus force the bail 89 rearwardly so as to add a unit in the "reset" counter. The number now standing 65 on the "reset" counter is the special reset

number for the sales to be accumulated during the period just begun.

When the cash drawer was opened the lower end of the locking lever 171 which engaged the rear end of the cash drawer was released so that the spring 164 (Fig. 4) rocked the locking levers 171 and 173 counter-clockwise as viewed in this figure to bring their respective locking shoulders over the flange of the key coupler, thereby preventing a succeeding operation of the machine until the cash drawer has been returned. When the cash drawer is returned it will again rock the locking levers clockwise freeing the key coupler and the keys for subsequent opera- 70 75 80

During the busy portion of the day's business it is sometimes desirable to permit the machine to be operated successively irrespective of the position of the cash drawer. To 85 this end the proprietor may insert his key in the lock 207 unlatching the lid 32 and permitting the released control lever to be adjusted to the "open drawer" position. This there is provided a lever 2441 which is control lever to co-operate with the beveled edge 175' of the upper extension 175 of the locking lever 173 thereby holding the lower ends of the locking levers rearwardly against the action of spring 164 thus preventing engagement of the levers with the flange of the key coupler while the cash drawer is open. This will permit successive operations of the keys even though the cash drawer is left open at 90 95 100 all times.

Whenever it is necessary to release the cash drawer for the purpose of making change, etc. the "No sale" key 33 is operated which operates the operating mechanism in the usual way, but since no indicator is elevated the previously raised amount indicators will be permitted to return to their concealed position indicating to the bystander that no cash was registered in the machine. During the depression of "No sale" key 33 the link 110 82 (Fig. 4) is operated and by means of the arm 81 attached to the shaft 80 rocks said shaft as well as the arm 79 (Fig. 3) connected thereto and by means of its co-operation with the bail 77 adds a unit in the "no 115 sale" counter wheels 74.

At the termination of a day's business it is desirable to obtain the necessary information in printed form and to this end the proprietor again inserts his key in the lock 120 206 and unlatches the cover 32 which, in addition, permits the control lever 165 to be shifted to the "total" position. During the time that this was being done the associated parts were moved from the position shown 125 in Fig. 4 to the position shown in Fig. 7. When the control lever was shifted to the "total" position the pin 198 carried by the extension 199 of the control lever 165 co-operated with the cam surface 177 and forced 130

both locking levers counter-clockwise bringing their respective locking shoulders over the flange of the coupler thereby locking the keys as long as the control lever is in this position.

Furthermore, when the control lever was shifted from the "closed drawer" position to the "total" position the projection 1651 (Fig. 7) co-operating with the pin 1652 operated the link 161 and by means of the operated drawer catch 157 permitted the cash drawer 154 to be expelled by means of the usual cash drawer spring.

As shown in Fig. 4 the resetting lever 95 is normally locked against operation by means of the stud 190 co-operating with the slot 189 formed in the member 188 attached to the resetting lever 95. When the control lever was moved rearwardly the pin 190 was elevated by means of the projection 194 of the member 191 attached to the control lever 165 co-operating with the pin 195 to rock the locking member 184 clockwise (as viewed in Figs. 4 and 7). Since the resetting lever 95 is now unlocked it can be operated to perform the resetting function but it is desirable to first perform a printing operation.

The printing button 127 which projects through the printer cover 31' is normally locked against operation by reason of the fact that the locking lugs 182 and 124 (Figs. 4 and 9) carried by the printer co-operate with their respective locking edges 183 and 187. When the member 184 was rocked clockwise to release the resetting lever it also brought slots 196 and 197 to register with the locking lugs 124 and 182 respectively, thereby unlocking the printing mechanism.

In order to take an imprint the button 127 is sharply depressed which will force the rubber impression blocks 104 rearwardly, forcing the paper against the inking ribbon and adjusted type members. After the printing operation has been performed, the printed portion of the strip, an example of which is shown in Fig. 18T, is withdrawn and detached from the rest of the roll.

In order to restore the totalizer elements to zero the resetting lever 95 is pushed rearwardly from the position shown in Fig. 7 to the position shown in Fig. 8. The segment 131 carried by the resetting lever 95 will rotate the gear 132 and the bent disk 135 to shift the shaft 58 laterally until the notches 141 (Fig. 21) co-operate with the resetting pawls 140 carried by the totalizer elements 57. At the same time that the gear 133 was being meshed with the gear 142 carried by the resetting shaft the gear 133 was rotating the gear 134 to take up the play normally existing between one end of the annular ring 137 carried by the gear 134 and the lug 138 integral with the collar 139 fast to the special counter resetting shaft 72.

Further rearward movement of the resetting

lever will rotate both of the resetting shafts so as to reset all of the totalizer elements and all of the special counter accumulating elements with, of course, the exception of the "reset" counter wheels. While the bent disk 73

135 was shifting the shaft 58 any friction between the bent disk and the collar 136 which would tend to rotate the shaft 58 is prevented by the lugs 147 and 148 co-operating with the fixed lug 146. Furthermore, as shown 75 in Fig. 25, the co-operation of the teeth on the pinion 142 with the concentric portion 1332 of the gear 133 after the shaft has been slightly shifted also serves to align said gear and in addition lock the shaft 58 against rotation while it is being shifted laterally. When the reset lever was forced rearwardly, the link 94 operated the arm 93 (Fig. 7) to force the pin 92 and the bail 89 to which it is attached so that the operating pawl associated with the "reset" counter would slip over the ratchet wheels into its forward cocked position. This also brought the lug 91 (Fig. 2) into contact with the pin 85 carried by the "customer" counter operating 83 bail so that this bail could also operate the "reset" counter and accumulate a unit during a subsequent operation of the machine.

While the resetting lever 95 was forced rearwardly to accomplish the resetting operation the cam edge 200 on the member 188 attached to the resetting lever 95 forced the stud 190 up against the shoulder 202 on the member 191 attached to the control lever. This locked the control lever in the "total" 103 position so that it could not be moved out of this position to unlock the amount keys while the resetting operation was being performed.

Since the member 184 was now rocked clockwise it brought the locking surface 201 on the member 184 into co-operation with locking lug 182; in a similar manner the locking lug 124 (Fig. 9) carried at the other side of the printer now co-operated with the locking surface 201 formed on the arm 186. This 103 prevented movement of the printing mechanism to take an imprint from the adjusted type carriers so long as the resetting lever was moved out of its normal position.

A full stroke of the resetting lever is insured by the co-operation of the pawl 152 (Fig. 6) with the teeth 151 formed on the member 150.

After the resetting operation has been performed the printer button is again depressed which will indicate on the record strip whether the resetting operation has been correctly performed. If this is the case, the record strip will bear an imprint similar to that shown in Fig. 18Z.

After the machine has thus been conditioned for accumulating sales pertaining to another period the control lever is moved up into the "lock register" position and the key in the lock 206 is rotated so as to lock the con-

trol lever in this position. The key is then detached from the lock and since the cover catches 219 are of the spring operated type the cover 32 can be closed so that it will be automatically locked.

The above pre-supposes that a single person has control over the resetting lever and the total printing button. When the machine is of the type known as the "auditor's" type a supplemental lock is utilized. In this type of machine the manager may have access to the control levers so as to move it into any desired position so as to condition the machine for operation in different ways or permit the machine to be adjusted so as to obtain the total of the sales. However, when the manager's lock 207 (Fig. 26) is operated it will not unlock the resetting lever 95, because the notch 224 in the resetting lever still operates with the periphery of the shiftable shaft 209.

At the termination of a desired period the auditor visits the store and inserts his key in his lock 226 (Fig. 26). This will unlatch the cover 32 and since the control lever is also unlocked it can be shifted to the "total" position. When the shaft 209 was shifted to the left (as viewed in Fig. 26) by the operation of this lock it brought the notch 213 to register with the notch 224 in the resetting lever 95 so that the resetting lever could be operated. The auditor may now first print the total and then operate the resetting lever to zeroize the various elements and after this has been accomplished he may operate the printing mechanism to obtain the "proof" of the "total". Any number of these can be obtained so that if so desired one can be given to the proprietor and the others used in any manner that the auditor wishes.

While the form of mechanism herein shown and described is admirably adapted to fulfill the objects primarily stated it is to be understood that it is not intended to confine the invention to the one form of embodiment herein shown, since it may be embodied in various forms, all coming within the scope of the claims which follow.

What is claimed is:

1. In a machine of the class described, the combination with a series of keys, a differential device operated by the keys, a pivoted frame carrying a series of totalizer elements driven by the differential device, a drive shaft, a box cam attached to the shaft, a depending arm having its upper end pivoted to a stationary frame and its lower end co-operating with the box cam, and a member attached at one end to said arm and at the other to said totalizer frame whereby the totalizer elements are drawn into and out of engagement with the differential device.

2. In a machine of the class described, the combination with a differential device controlled by a series of keys, a totalizer, a cam

for engaging the totalizer with the differential device, a resetting lever for the totalizer pivotally mounted on a shaft, a projection, on said lever near its pivotal connection, and a cutaway portion in said cam to receive the projection when the cam is in its normal position.

3. In a machine of the class described, the combination with a differential device controlled by a series of keys, a totalizer, a cam for engaging the totalizer with the differential device, and a resetting lever having a portion adapted to directly engage said cam so as to prevent a movement of one if the other should be operated.

4. In a machine of the class described, the combination with a totalizer frame carrying a shaft, adapted to be rotated, means for rocking said totalizer frame, and rigid means carried by a fixed portion of the machine frame co-operating with said shaft whereby the shaft will be locked against rotation during the rocking of said totalizer frame.

5. In a machine of the class described, the combination with a plurality of totalizer elements mounted upon a shaft, resetting means for the totalizer elements carried by said shaft, a second shaft parallel to the first mentioned shaft carrying a series of special counters, resetting means therefor carried by the second shaft, and a lever for rocking both shafts to zeroize the totalizer elements and counters.

6. In a machine of the class described, the combination with two parallel shafts each carrying a series of accounting elements, resetting means on one shaft normally out of connection with the accounting elements, carried thereby, resetting means on the other shaft always in effective position, a single lever, and means under control of said lever for first establishing an operative connection between said resetting means and elements of the first shaft and then rotating both shafts to zeroize the elements.

7. In a machine of the class described, the combination with a plurality of resetting shafts, each carrying a series of accumulating elements, a pinion carried by each resetting shaft, a gear normally in mesh with the pinion carried by one of the shafts, but out of mesh with another pinion, a lever, and means operated by said lever for meshing the gear with the last mentioned pinion carried by another resetting shaft and thereafter rotating all of said pinions and shafts.

8. In a machine of the class described, the combination with a plurality of resetting shafts carrying a plurality of accumulating elements, resetting devices for the elements carried by each shaft the resetting devices of one shaft being normally out of connection with their associated elements, and a resetting lever provided with devices for first establishing this connection and then rotating

all of said shafts, said lever having a lost motion connection with all but said first mentioned shaft.

9. In a machine of the class described, a plurality of shafts, a plurality of accounting members mounted on each shaft, means for operating said members additively, co-acting means carried by said shafts and members whereby said members may be restored to normal positions upon rotation of said shafts, the coacting means between the members and one of said shafts being normally out of operative relationship, and a resetting mechanism for first establishing such relationship and then simultaneously rotating all of said shafts, one shaft being rotated in the direction of additive movement of the members mounted thereon and another shaft being rotated in a direction reverse to the additive movement of the members mounted thereon.

10. In a machine of the class described, the combination with a resetting shaft, a plurality of totalizer elements mounted thereon, a lever, a pinion rotated by said lever and normally out of engagement with a pinion carried by the resetting shaft, and means controlled by the lever for establishing an engagement between said pinions.

11. In a machine of the class described, the combination with a resetting shaft carrying a plurality of totalizer elements, resetting devices carried by the elements normally out of connection with the resetting shaft, a pinion carried by the shaft normally out of connection with a drive pinion and a lever having means connected therewith for establishing both connections.

12. In a machine of the class described, the combination with a resetting shaft carrying a plurality of totalizer elements, resetting devices carried by the elements normally out of connection with the resetting shaft, a pinion carried by the shaft normally out of connection with a drive pinion, and a lever having means connected therewith for establishing both connections, and then operating the drive pinion to rock the shaft to reset the totalizer elements.

13. In a machine of the class described, the combination with a series of totalizer elements, a shaft upon which the totalizer elements are mounted and adapted to reset them to zero, a grooved collar surrounding said shaft and rigid therewith, a bent disk engaging said groove, a lever for rotating said disk thereby moving said shaft longitudinally, and means for retaining the shaft locked during a preliminary movement of the lever and then unlocking it to permit the shaft to be rotated to reset the totalizer elements.

14. In a machine of the class described, a fixed machine frame, the combination with a shaft carrying a plurality of notches, totalizer elements mounted on the shaft, pawls at-

tached to the elements normally out of operative relationship with the notches in the shaft, a lever for shifting the shaft to establish this relationship, and means comprising a projection integral with said machine frame, said projection cooperating with a pair of lugs on said shaft for locking the shaft against rotation while it is being shifted.

15. In a machine of the class described, the combination with a shaft carrying a plurality of notches, totalizer elements mounted on the shaft, pawls attached to the totalizer elements normally out of operative relationship with the notches, a lever, a bent disk and gear segment operated by said lever for first establishing such operative relationship and then rotating the shaft, and means for normally locking the shaft against rotation during the time that such operative relationship between the notches and pawls is being established, and additional means comprising a plain portion of said disk for holding the said shaft unlocked during its rotation.

16. In a machine of the class described, the combination with a shaft carrying a plurality of notches, totalizer elements mounted on the shaft, pawls attached to the totalizer elements normally out of operative relationship with said notches, a lever, a bent disk operated by said lever for establishing such operative relationship, and a plurality of means having overlapping periods of action for locking the shaft while it is being moved to establish the operative relationship between the notches and pawls said bent disk having a pair of plain portions, one for holding said shaft in engagement with said pawls and the other holding said shaft in its normally disengaged position.

17. In a machine of the class described, the combination with a shaft carrying notches, a plurality of totalizer pinions carried by said shaft and having pawls normally out of engagement with the notches, a gear carried by the said shaft, a disk having gear teeth around a portion of its periphery for driving the gear and shaft, a cam attached to said disk for shifting the shaft to establish a connection between the notches and pawls, and means formed on said disk co-operating with the first mentioned gear to align and lock the shaft while it is being shifted.

18. In a machine of the class described, the combination with a shaft carrying notches, a plurality of totalizer pinions carried by said shaft, and having pawls normally out of engagement with the notches, a gear carried by the said shaft, a disk having gear teeth around a portion of its periphery for driving the gear and shaft, a cam attached to said disk for shifting the shaft to establish a connection between the notches and pawls, means formed on said disk co-operating with the first mentioned gear to align and lock the shaft while

- it is being shifted, and a lever for operating the disk and cam.
19. In a cash register, the combination with a plurality of totalizer elements carried by a shaft, a series of special counters mounted on a shaft parallel to the first mentioned shaft, a lever, means actuated by said lever for conditioning one of said counters for operation, said lever being adapted to reset all the totalizer elements and some of the special counters and simultaneously control the operation of said special counter, and means requiring an operation of the machine to actuate said special counter.
- 15 20. In a cash register, the combination with a resetting lever, a special counter for indicating the number of effective operations of the lever, an operating mechanism, and connections therefrom for operating the counter, said connections requiring an operation of the lever before they are rendered effective to cause said counter to indicate the number of effective operations of the lever, and means for retaining said connections in effective position regardless of the number of successive operations of said lever
- 20 21. In a cash register, the combination with an operating mechanism therefor, a special counter indicating the number of times the operating mechanism has been actuated, actuating means for said counter, a lever, a counter associated with the lever, and means under control of said lever and operated by the actuating means of the first mentioned counter for operating the second.
- 35 22. In a cash register, the combination of a reset counter, operating means therefor, a customer counter, operating means therefor, a lug carried by the reset counter operating means, and an extension carried by the customer counter operating means, the relation of the parts being such that the extension co-operates with the lug to operate the reset counter operating means upon certain operations of the customer counter operating means.
- 40 23. In a machine of the class described, the combination with a series of amount keys, a series of totalizer elements adapted for printing, means controlled by the keys for differentially operating the totalizer elements, an operating mechanism, a special counter for registering the number of operations of the operating mechanism, a No sale key, a counter for registering the number of operations of the No sale key, a resetting lever, a counter controlled by the operations of the resetting lever to count the number of resetting operations, printing means carried by each of said counters, special printing members adjacent each special counter and totalizer to identify the various totals, a printer, and a manipulative device for simultaneously effecting printing impressions from the special counters and totalizer elements upon a single record medium.
- 45 24. In a cash register, the combination with an operating member, operating keys for reciprocating the operating member, a plurality of rockable locking levers adapted to move over and lock the operating member, and a spring connection between said levers for controlling certain movements of said levers.
- 50 25. In a cash register, the combination with an operating member, operating keys for reciprocating the operating member, a plurality of rockable juxtaposed locking levers adapted to move over and lock the operating member, and a connection between said levers whereby they can be moved independently of each other or as a unit.
- 55 26. In a cash register, the combination with an operating member, a plurality of rockable locking levers adapted to move over and lock the operating member, a connection between the levers permitting them to move singly, or simultaneously as a unit and a manipulative device for positively moving one of the levers to locking position.
- 60 27. In a cash register, the combination of an operating member, a cash drawer, a plurality of locking levers for said operating member, one of said levers contacting with the cash drawer when the latter is closed, a connection between the levers whereby they tend to move as a unit, and a spring adapted to rock both locking levers to locking position when the cash drawer is open.
- 65 28. In a cash register, the combination of an operating member, a cash drawer, a plurality of locking levers for said operating member, one of said levers contacting with the cash drawer, a connection between the levers tending to swing them as a unit, a spring tending to rock the locking levers to lock the operating member when the cash drawer is open, and a manipulative device to prevent the spring from rocking them to locking position while the cash drawer is open.
- 70 29. In a cash register, the combination of a manipulative device, a cash drawer, an operating member, a plurality of inter-connected locking levers for said operating member one being under control of the cash drawer and another under control of the manipulative device, and means under control of the manipulative device for positively moving its associated locking lever to locking position, the connection between said levers permitting the cash drawer to move its locking lever to unlocking position without affecting the movement of the remaining locking levers.
- 75 30. In a cash register, the combination with a manipulative device movable to three positions, an operating member, a locking lever adapted to co-operate with the operating member, a spring for urging the lever into locking position, and means carried by

- the manipulative device co-operating with the locking device whereby the manipulative device in one position will positively move the locking lever to locking position, in the 5 second position will hold the lever out of locking position and in the third will permit the spring to move the locking lever to locking position.
31. In a cash register, the combination with 10 an operating member, a manipulative device movable to four positions, a locking lever adapted to lock the operating member, a spring urging the lever to locking position, and means carried by the manipulative device 15 co-operating with the lever whereby the manipulative device in the first position will positively move the locking lever to lock the operating member, in the second will hold the lever out of locking position, in the third will 20 permit the spring to move the lever to locking position and in the fourth again positively move the locking lever to locking position.
32. In a cash register, the combination with 25 an operating member, a locking lever adapted to lock the operating member, a manipulative device movable to various positions, and means carried by the manipulative device and co-operating with the lever whereby the latter 30 will be positively moved to locking position at the extreme ends of the movement of the manipulative device.
33. In a cash register, the combination with 35 an operating member, a plurality of locking levers adapted to move over the operating member, a spring for urging both locking levers to locking position, a manipulative device, means carried thereby for holding one of the levers in unlocking position, an interconnected spring between the locking levers 40 tending to draw the other lever into locking position, and means carried by the lever held in unlocking position for preventing the other lever from moving to locking position.
34. In a cash register, the combination with 45 an operating member, a cash drawer, a plurality of independently mounted locking levers one of which co-operates with the cash drawer, a manipulative device for controlling 50 the movement of another of said levers to locking position, and connections permitting the cash drawer to move the first mentioned lever to unlocking position either jointly with the second mentioned lever or without 55 affecting the position of the second lever depending upon the condition of the manipulative device.
35. In a cash register, the combination of a 60 plurality of manipulative devices, normally locked against movement, a cover for concealing the manipulative devices, a plurality of locks, and means controlled by said locks to release the cover, and to unlock one or all of the manipulative devices depending upon which lock is operated.
36. In a cash register, the combination of a plurality of manipulative devices, a rod for normally locking said devices, a plurality of locks having connections to shift said rod in either direction, and formations on said rod whereby when the rod is shifted one way it will unlock only one manipulative device but when shifted the other way it will unlock both manipulative devices. 70
37. In a machine of the class described, a total printing control member, a resetting control member, a shiftable member normally preventing the operation of either member, and a pair of locks co-operating with said shiftable member so that operation of one lock will release the total printing control member and operation of the other lock will release the resetting control member. 75
38. In a machine of the class described, a totalizer, means for printing the totals accumulated thereon, lock controlled means for clearing the totalizer, a common control element for controlling the operation of said total printing and said clearing means, a lid normally concealing said total printing means, said clearing means and said control element, a lock adapted to release said lid to permit access to the members specified, and a second lock adapted to release said lid and simultaneously release said clearing means 80 for operation. 85
39. In a cash register, the combination of a plurality of normally locked manipulative devices, a cover for concealing the manipulative devices, and a plurality of locks having common connections to release the cover, said connections including means for simultaneously releasing one or all of the manipulative devices depending on the lock which has been operated. 90 100
40. In a cash register, the combination of a plurality of manipulative devices, a cover for concealing the manipulative devices, a latch for the cover, a rod for normally locking the manipulative devices and having connections to operate the latch, and a plurality of locks for so shifting the rod that either can operate the latch while one or all of the manipulative devices are released depending on the lock which has been operated. 105 110
41. In a machine of the class described, a cabinet to conceal the working parts, a lid hinged to said cabinet and adapted to conceal or expose a portion of the working parts, a latch normally retaining said lid in closed position, a rod shiftable in either direction from normal position, connections from said rod to control said latch, and a pair of locks adapted to move said rod in either direction to cause release of said latch. 115 125
42. In a cash register, the combination with a movable printing frame carrying a locking lug, a locking member formed with a plurality of locking edges and an intermediate notch, a lever for controlling the locking 130

member so that one of its locking edges is brought into co-operation with the lug on the printer frame so as to lock the printer when the lever is in one position whereas the member is so positioned that its notch co-operates with the lug to unlock the printer when the lever is in another position, and a supplemental lever for moving the member so that the other locking edge co-operates with the lug to lock the printer.

43. In a cash register, the combination of a movable printer carrying a locking lug, a member co-operating with the lug to either lock or unlock the printer, a lever for moving the member to either lock or unlock the printer, a supplemental lever for moving the member to lock the printer when it is unlocked by the first lever, and means carried by the member for locking the first mentioned lever when the supplemental lever is operated.

44. In a cash register, the combination of a printer, a series of keys, a resetting lever, a control lever and connections movable to one position for unlocking the keys and locking both the resetting lever and printer and to another position to lock the keys and unlock the printer and resetting lever, and means controlled by the printer for locking the control lever and resetting lever while the printer is being operated.

45. In a cash register, the combination of a printer, a series of keys, a resetting lever, a control lever and connections movable to one position for unlocking the keys and locking both the resetting lever and printer, and to another position to lock the keys and unlock the printer and resetting lever, means controlled by the printer for locking the control lever and resetting lever while the printer is being operated, and means governed by the resetting lever for locking the control lever.

46. In a cash register, the combination of a printer, a series of keys, a resetting lever, a control lever and connections movable to one position for unlocking the keys and locking both the resetting lever and printer, and to another position to lock the keys and unlock the printer and resetting lever, means controlled by the printer for locking the control lever and resetting lever while the printer is being operated, and means governed by the resetting lever for locking both the control lever and printer.

47. In a machine of the class described, a totalizer, means for entering items in said totalizer, means for printing the totals of amounts entered, means for clearing the totalizer, a movable control member, and means operated by said control member upon movement of certain positions for preventing either total printing or clearing, said means serving also to prevent movement of either

the total printing or the clearing means when the other is being operated.

48. In a machine of the class described, a totalizer provided with printing type, item entering means, means for printing from said totalizer upon a record material, clearing means for said totalizer, a control lever for determining the various functions to be performed, and interlocking means directly controlled by said lever for permitting the operation of any one but not more than one of said item entering, total printing and clearing means at a time.

49. In a machine of the class described, a totalizer, means for printing totals standing on the totalizer, means for resetting said totalizer, a plate normally adapted to prevent operation of either said total printing or said resetting means, said plate serving also as an interlock between said means whereby when the plate is shifted to one of its positions one of said means may be operated to the exclusion of the other.

50. In a machine of the class described, a control lever, a resetting lever, a total printing member, and a pivoted element provided with means for selectively preventing operation of said levers and member according to the position of said element, said element having one position in which one of said levers and member may be operated to the exclusion of the others.

51. In a machine of the class described, a control lever, a resetting lever, a total printing member, a shiftable interlocking element, and connections between said element and said levers and member so constructed that in one position of said element one of said levers and member may be operated to the exclusion of the others and in another position of said element another of said levers and member may be operated while the others are locked against movement.

52. In a cash register, the combination of an operating member, a manipulative device, a cash-drawer, a plurality of rockable locking levers for the operating member, one of said levers being operated by the drawer to release the operating member, the other of said levers being positively operated by said manipulative device to lock said operating mechanism, and means connecting said levers causing movement thereof as a unit.

53. In a cash register, the combination of a plurality of manipulative devices, a movable member normally engaging said devices to lock the same against operation, means provided on said member for unlocking said devices, a plurality of key actuated locks controlling the movement of said member, connections between said locks and member so arranged that operation of one of said locks will control the movement of said member to release one of said devices and that operation of another of said locks will con-

trol the movement of said member to release all of said devices.

54. In a cash register, the combination of a movable printer carrying a locking lug, a movable member, means on said member for preventing movement of said printer, a notch in said member which is adapted to register with said lug to permit movement of said printer, a lever for moving said member to either locking or unlocking position, and a supplemental lever for moving said member to lock the printer when it is unlocked by the first-mentioned lever.

55. In a cash register, a shaft, a series of type carrying totalizer elements mounted on said shaft, a second shaft parallel to said first-mentioned shaft, a plurality of type carrying special counters mounted on said second shaft, one for registering the number of operations of the machine and another for registering the number of no sale operations of the machine, a platen having a plurality of impression blocks, and means for actuating said platen to effect simultaneous printing from said elements and special counters.

56. In a machine of the class described, a cabinet, a series of amount keys, a series of type carrying totalizer elements, means controlled by the keys for differentially operating the totalizer elements, a series of type carrying special counters for registering various kinds of operations of the machine, means for taking impressions from said elements and counters, manipulative means for operating said impression means, a normally locked hood on said cabinet for concealing said manipulative means, and means for unlocking said hood.

57. In a cash register, the combination of a plurality of printing totalizer elements mounted on a shaft, a plurality of printing counter elements mounted on a shaft parallel to said first-mentioned shaft, means for adjusting said counter elements, and a platen carrying a plurality of impression blocks for effecting printing directly from said elements.

58. In a cash register, the combination with a lever, a special counter provided with type for registering the number of effective operations of the lever, means positioned by said lever for actuating said counter, an operating mechanism, a special counter provided with type for registering the number of operations of the operating mechanism, means under control of the operating mechanism engaging said first mentioned means thereby causing simultaneous operation of said counters and means for taking printing impressions from said counters.

59. In a cash register, the combination of a movable printer, a lever having a plurality of positions of adjustment for controlling the various kinds of operations of the machine,

means actuated by said lever when moved to one position only for unlocking the printer, and a projection carried by the printer side frame for preventing movement of said lever while the printer is being operated.

60. In a cash register, the combination of a printer, a series of keys, a control lever movable to a plurality of positions of adjustment for controlling the various kinds of operations of the machine, and connections from said lever so constructed and arranged as to cause locking of the keys and unlocking of the printer when said lever is moved to one position, and to cause unlocking of the keys and locking of the printer when said lever is moved to another position, and means controlled by the printer for locking the control lever while the printer is being operated.

61. In a cash register, the combination of a pivotally mounted total printing control device, a pivotally mounted reset device, a shiftable member adapted to normally engage said devices to lock the same against operation, means provided in said shiftable member permitting movement of said devices, and a single lock for moving said shiftable member to release said devices for operation.

62. In a machine of the class described, the combination of a plurality of type carrying totalizer elements, a series of amount keys, means operated by said keys for differentially actuating each of said elements, a No sale key, a type carrying counter operated by said No sale key at each operation of said key, means for taking printing impressions from said elements and counters upon a record material, and means for preventing the simultaneous operation of said printing means and said keys.

63. In a machine of the class described, a shaft, a plurality of type carrying totalizer elements mounted on said shaft, a series of amount keys, means controlled by said keys for differentially operating the totalizer elements, a No sale key, a type carrying counter for registering the number of operations of said No sale key, a resetting means for said totalizer, a type carrying counter for registering the number of effective operations of said resetting means, a shaft parallel to said first mentioned shaft supporting said counters, special printing members adjacent each special counter and totalizer to identify the various totals and means for taking printing impressions from the totalizer elements, the counters, and the special printing members.

64. In a machine of the class described, a plurality of type carrying totalizer elements, a series of amount keys, means controlled by said keys for differentially operating the totalizer elements, a series of special counters mounted in parallel relationship with respect to said totalizer elements, special printing members adjacent each special counter and totalizer to identify the various totals

registered therein, and means for effecting printing impressions from the totalizer elements, the counters and the special printing members upon a single record material.

65. In a machine of the class described, a plurality of type carrying totalizer elements, a series of amount keys for operating the machine, devices controlled by said keys for differentially operating said totalizer elements, means for operating the machine without effecting accumulations in said totalizer elements, a type carrying counter, means for registering a unit in said counter at each operation of the machine, a second type carrying counter, means for registering a unit in said second counter upon operation of said first mentioned means only, special type members adjacent each counter and the totalizer to identify the totals accumulated therein, and means for taking printing impressions from said totalizer elements, counters, and special type members upon a single record material.

66. In a cash register the combination with a lever, a special counter provided with printing type, operating means for said special counter, means under control of the lever for adjusting the operating means, means independent of the lever for holding the operating means in adjusted position, a main operating mechanism, means under the control of the operating mechanism for operating the special counter operating means after it has been adjusted by the lever and means for taking impressions from said counter.

67. In a cash register, the combination of a plurality of adjustable manipulative devices, a longitudinally shiftable member adapted to engage said device to lock the latter against operation, one of said manipulative devices being adapted to be locked thereby in any one of a plurality of positions of adjustment, said shiftable member being cut away to permit movement of said devices, and a single lock for moving said member to condition said devices for operation.

68. In a cash register, the combination with item entering means, a plurality of totalizer elements actuated thereby and carried by a shaft, a plurality of counter elements mounted on a shaft parallel to the first mentioned shaft and also actuated by said item entering means, impression means for printing directly from all of said elements, and means for simultaneously resetting said counter and totalizer elements.

69. In a cash register, the combination with item entering means, a plurality of totalizer elements actuated thereby and carried by a shaft, a plurality of counter elements mounted on a shaft parallel to the first mentioned shaft and also actuated by said item entering means, a separate impression means for printing from each of said shafts, and means responsive to the operation of one of said im-

pression means, for compelling the printing by the other impression means before any of the totalizers or counter elements are rotated to new position.

70. In a register having a totalizer and means for resetting said totalizer to zero, the method of counting the resetting operations which comprises conditioning a reset counter for operation whenever the totalizer is reset, and advancing the reset counter to add a unit in response to a subsequent advancement of the totalizer.

71. In a register, a totalizer, item entering means and a reset device for actuating said totalizer, a reset counter for counting the effective operations of said reset device, operating means for the reset counter movable through a cycle which comprises a plurality of positions of rest, means requiring the operation of said reset device for moving the counter operating means to one of said positions, and means requiring the operation of the item entering means for moving the counter operating means to another one of said positions, said counter being operated by each cycle of said counter operating means.

72. In a cash register, an operating mechanism, a cash drawer, means for locking the operating mechanism until the cash drawer is closed, said means comprising a locking lever adapted to be moved by the cash drawer to unlocking position, a second locking lever also adapted to lock the operating mechanism, yieldable means tending to move both of said locking levers to locking position, a control member movable to a plurality of positions of adjustment, said control member having means for disabling said second locking lever without disabling the first locking lever when the control member is in one position of adjustment, and for disabling both of said locking levers when the control member is in a different position of adjustment.

73. A cash register as defined in claim 72, in which the control member has a cam engagement with the second locking lever for moving the latter out of locking position with respect to the operating mechanism.

74. In a machine of the class described, the combination of a control member, a shaft supporting said control member, a second shaft, a plurality of locking levers pivoted on said second shaft, an operating mechanism, connections between said locking levers and control member so constructed and arranged that when said control member is moved to one of its positions of adjustment, one of said levers is moved into locking engagement with said operating mechanism, and when said control member is moved to another position of adjustment, another of said levers is conditioned for locking said operating mechanism; a cash drawer, means for causing said last mentioned lever to move into locking engagement with said operating mechanism

when said drawer is in open position, and means for disabling all of said locking levers when said control member is moved to still another position of adjustment.

75. In a machine of the class described, the combination of a control member, a plurality of locking levers, an operating mechanism, connections between said locking levers and said control member so constructed and arranged that when said control member is in one of its positions of adjustment, one of said levers is moved into locking engagement with said operation mechanism, and when said control member is moved to another position of adjustment, another of said levers will be conditioned for locking said operating mechanism, a cash drawer, means for causing said last mentioned lever to lock said operating mechanism when said drawer is opened, means provided on said last mentioned lever adapted to be engaged by said drawer when the latter is moved to closed position, to release said lever from locking engagement with said control member, and means for disabling all of said locking levers when said control member is moved to still another position of adjustment.

In witness whereof I have signed my name
hereto this 4th day of March, 1925.

CHARLES W. GREEN.

CERTIFICATE OF CORRECTION.

Patent No. 1,873,760.

August 23, 1932.

CHARLES W. GREEN.

It is hereby certified that error appears in the printed specification of the above numbered patent requiring correction as follows: Page 3, line 128, for "rest" read reset; page 18, line 90, strike out the words "there is provided a lever 2441 which is" and insert instead will permit the stud 181 (Fig. 4) on the; page 21, line 100, claim 16, insert a comma after "pawls"; and that the said Letters Patent should be read with these corrections therein that the same may conform to the record of the case in the Patent Office.

Signed and sealed this 29th day of November, A. D. 1932.

M. J. Moore,
Acting Commissioner of Patents.
